REFRIGERATING MACHINE

Donald H. Gaston, Evansville, Ind., assignor to
General Electric Company, a corporation of
New York

Application June 16, 1938, Serial No. 214,090

43 Claims.

(Cl. 62—4)

My invention relates to refrigerating machines, and more particularly to refrigerating machines for automatically and continuously freezing ice or other materials.

Restaurants and similar establishments frequently require large quantities of ice for beverages and the like. If large cakes of ice are purchased from a commercial refrigerating plant to supply this need, the cakes must be broken up into pieces of convenient and usable size while the handling and storage of the ice presents obvious inconveniences and expense.

Most mechanical refrigerators designed for household use are provided with several freezing trays in which cubes of ice or the like may be frozen. These cubes are of a convenient size for use in cooling beverages or the like, and such an arrangement supplies sufficient ice for the ordinary household. It is, however, frequently inadequate for commercial establishments in which large quantities of ice are required. In addition, the ice cubes frozen in such a tray must be individually removed therefrom and even though this is not so serious an objection insofar as household use is concerned, where only a relatively small number of cubes are used, it becomes of increased importance in case it is necessary to handle a large number of ice cubes.

It is an object of my invention to provide a refrigerating machine in which provision is made for continuously freezing successive quantities of ice or other material and then ejecting the same when frozen, the operation of the machine preferably being entirely automatic.

A further object of my invention is to provide an improved refrigerating machine for automatically freezing successive quantities of ice or other material and for storing the material so frozen in a cooled compartment to prevent the melting of the frozen material.

A further object of my invention is to provide an improved refrigerating machine having a single refrigerant liquefying unit and a plurality of refrigerant evaporators which may be selectively supplied with refrigerant from the refrigerant liquefying unit, one of the evaporators being utilized to freeze successive quantities of material in a mold from which they are ejected upon being frozen, and another of the evaporators being utilized to cool a compartment in which the frozen material is stored.

A further object of my invention is to provide an improved arrangement for supplying successive measured quantities of liquid to a

mold in which the liquid is frozen and from which it is then removed.

A further object of my invention is to provide a refrigerating machine for freezing purposes, and utilizing the action of the refrigerant for ejecting the material frozen by the machine.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawings in which Fig. 1 is a side elevation, partly in section, of a refrigerating machine embodying my invention, the refrigerating machine being mounted in a portable cabinet; Fig. 2 is a front elevation of the refrigerating machine and cabinet shown in Fig. 1, a portion of the door of the cabinet and a portion of the ice storage drawer being broken away better to illustrate the interior arrangement of the refrigerating machine; Fig. 3 is a diagrammatic representation of the refrigerating machine shown in Fig. 1 and the control circuit therefor; Fig. 4 is an enlarged side elevation, partly in section, of the liquid measuring supply apparatus of the refrigerating machine shown in Fig. 1; Fig. 5 is a sectional end elevation of a portion of the liquid supply apparatus along the line 5—5 of Fig. 4; Fig. 6 is an enlarged side elevation, partly in section, of one of the banks of freezing molds of the refrigerating machine shown in Fig. 1; Fig. 7 is a plan view, partly in section, of the bank of freezing molds shown in Fig. 6; Fig. 8 is a front elevation of a refrigerator partly broken away and having a refrigerating machine associated therewith embodying a modification 40 of my invention; Fig. 9 is a side elevation of the refrigerator shown in Fig. 8 also partly broken away to show the construction of the refrigerating machine; Fig. 10 is a schematic perspective view of the refrigerating machine shown in Figs. 8 and 9; Fig. 11 is a perspective view partly in section showing the construction of the freezing molds utilized in the machines shown in Figs. 8, 9, and 10; Fig. 12 is a diagrammatic perspective view of the arrangement 50 of the refrigerating coils utilized for freezing the contents of the molds shown in Figs. 10 and 11; and Fig. 13 is a side elevation, in section, of the liquid measuring vessel shown in Fig. 10.

In Figs. 1 to 7, inclusive, I have illustrated one embodiment of my invention. I have shown a

cabinet including a freezing compartment 15 and a plurality of banks of freezing molds 30 and 31. The lower portions of the banks of molds are surrounded by a metal casing 39 which contains an evaporator coil 59. Refrigerant is supplied to the evaporator coil 59 from a refrigerating liquefying unit 32 located in the machinery compartment 16. After the contents of the molds are frozen, they are softened about the edges by heat from electric heating element 92 and ejected therefrom by a suitable ejecting mechanism including a solenoid and pistons 84, the operation of which is dependent upon the operation of the freezing means. A liquid supply tank 37 and liquid measuring vessels 118 and 119 and 120 and 121 are provided to supply liquid to be frozen to the banks of molds as soon as the frozen material has been ejected therefrom. The frozen material after it has been ejected from the molds is stored in the bottom of the compartment 15 until extracted for use. In the modification illustrated in Figs. 8 to 13, inclusive, I have shown a modified control and liquid supply means and an ejecting means operated by a fluid motor utilizing the high pressure liquid refrigerant as an operating fluid is substituted for the solenoid operated ejecting means. By providing a flexible, non-heat conducting lining 325 for example, rubber, in the molds, the electric heating coil may be omitted.

I have shown in Figs. 1 and 2 a self-contained refrigerating machine mounted in a portable cabinet, the refrigerating machine being adapted to automatically and continuously freeze successive quantities of ice or the like. The cabinet is rectangular in outline and is of the same general type as is ordinarily used for household refrigerators. The cabinet includes a rectangular outer sheet metal shell 10 having a rectangular opening in the top thereof surrounded by a vertical flange 11. The shell 10 is provided with a horizontal imperforate sheet metal partition 12 therein, which extends entirely across the interior of the lower portion of the cabinet. The front and rear edges of the partition 12 are provided with downwardly extending flanges 13 and 14 respectively, which are welded or otherwise secured to the front and rear walls of the shell 10. The partition 12 divides the space within the rectangular shell 10 into an upper compartment 15 and a lower machinery compartment 16 respectively. The compartment 15 is provided with an open top inner liner 17 which covers the bottom and side walls thereof and is also provided with a rectangular aperture or door-opening 18 in the front wall thereof. The liner 17 is surrounded by heat insulation 19 and the door-opening 18 in the front wall thereof is closed by a heat insulated door 20. The edge of the heat insulation 19 surrounding the opening in the top of the liner 17 is covered by a cloth band 21. The front and rear walls of the shell 10 extend downwardly only to the bottoms of the flanges 13 and 14 respectively of the horizontal partition 12.

The cabinet thus formed is supported upon and reinforced by a suitable base 23. The base 23 is made up of a rectangular frame formed by horizontal angle irons 24 supported on legs 25, the base being surrounded on the front and sides by a sheet metal mopboard 26 secured to the base. The rear side of the base 23 is open. The mopboard 26 has an inset portion 27 in the front thereof which permits cooling air to enter the machinery compartment 16 at 28. The horizontal angle irons 24 are welded or otherwise

rigidly secured to the legs 25. The front, rear, and bottom of the machinery compartment 16 are thus open. The front wall of the machinery compartment 16 is covered by a removable panel 5 29 which extends entirely across the same. When the door 20 and panel 29 are closed, the front of the cabinet thus presents a smooth surface which may be easily cleaned and which has a pleasing appearance.

10 The portable cabinet described above is provided with a refrigerating machine embodying my invention which includes banks of freezing molds 30 and 31 positioned in the compartment 15. Material, such as water, automatically supplied to the banks of molds 30 and 31 in measured quantities, as hereinafter described, is frozen by the absorption of heat therefrom by vaporizable liquid refrigerant circulated through evaporator coils, which are arranged in heat exchange relation with the molds. The liquid refrigerant is supplied to the evaporator from a refrigerant liquefying unit 32 mounted in the machinery compartment 16. After the contents of the freezing molds are frozen, they are ejected therefrom by a suitable ejecting arrangement hereinafter described and the frozen material is then stored within the compartment 15 until it is desired to use the same.

30 The banks of molds 30 and 31 are substantially identical. As best shown in Figs. 6 and 7, the bank, or row of molds 30, includes a plurality of vertical cylindrical pockets or molds 33. The upper edges of the molds 33 are flared outwardly to form lips 34 which are welded, or otherwise 35 rigidly secured, to the adjacent edges of a series of longitudinally aligned holes formed in a rectangular cover plate 35. A rectangular depression 36 is formed within the periphery of the cover plate 35 and extends over substantially 40 the entire surface thereof. This depression 36 assists in filling the molds with liquid to be frozen, in that the liquid may be directed into the depression 36 and is then distributed therethrough to the molds 33 through a series of 45 grooves 37 formed in the cover plate 35 at the bottom of the depression 36. The opposite ends of the grooves 37 register with slots 38 formed in the upper edges of the molds 33. The lower portions of the molds 33, as well as the heating and 50 cooling apparatus therefor which is hereinafter described, are surrounded by a rectangular metal casing 39. The cover plate 35 is provided with a depending peripheral flange 40 which is tightly fitted about the adjacent upper edges of the casing 39 and frictionally engages the same.

55 The ends of the casing 39 are secured to substantially rectangular end plates 41 shown in Figs. 1 and 2. The rear edges of the end plates 41 are secured to angle irons 42 having inwardly 60 extending upper ends 43. The upper edges of the end plates 41 are secured to the opposite ends of a horizontal angle iron 44. A horizontal plate 45 having an upstanding peripheral flange 46 forms the bottom of the frame structure in which the banks of molds 30 and 31 are mounted. The lower edges of the end plates 41 are welded, or otherwise rigidly secured, to the flange 46 of the bottom plate 45. The bottom plate 45 also forms a drip-pan in which any moisture falling from the molds 33, or mold casings 39 is collected.

65 The bottom plate 45 is in turn supported by a frame structure, which includes a plate 47 secured to the lower side thereof and having a downwardly extending flange 48. The flange 48 formed on the plate 47 is positioned in a groove

49 formed in the upper edge of a strip of heat insulating material 50, which extends entirely about the flange 48. A second horizontal plate 51 is provided with an upstanding peripheral flange 52 which is fitted in a groove 53 formed in the lower edge of the insulating strip 50. A series of vertical plugs 54 of heat insulating material are arranged between the adjacent portions of the plates 47 and 51 and the opposite ends of the plugs 54 are secured to the adjacent portions of the plates 47 and 51 by screws 55 and 56, respectively. The screws 55 also extend through the bottom plate 45 and the plates 45, 47, and 51 are thus firmly secured together. A layer of heat insulating material 57 is arranged in the space between the plates 47 and 51. A series of vertical angle irons 58 are attached to the corners of the plate 51 and support the frame structure thus formed on the bottom of the compartment 15.

The contents of the molds 33, shown in Figs. 6 and 7, is cooled by liquid vaporizable refrigerant circulated through refrigerator evaporator conduits 59 which are helically wound about the outer walls of the molds. The evaporator conduits 59 are preferably substantially square in cross-section and the inner sides thereof are brazed, or otherwise tightly secured to the outer walls of the molds 33, in good heat conducting relationship therewith. The evaporator coils 59 extend through each bank of molds 30 and 31 and are preferably made of a continuous section of conduit so that the coils of evaporator conduit in each bank are connected in series relation. The series of evaporator coils 59 in each of the banks 30 and 31 are in turn connected in series relation by a conduit 60.

Liquid refrigerant is supplied to the evaporator coils 59 surrounding the molds 33 from the refrigerant liquefying unit 32 located in the machinery compartment 16. The refrigerant liquefying unit includes a reciprocating type refrigerant compressor 61 in which vaporized refrigerant, such as sulphur dioxide, is compressed. The compressor 61 is driven by an electric driving motor 62 connected thereto through a belt 63 which extends over a driving pulley mounted on the compressor drive shaft and a motor pulley mounted on the end of a motor shaft. Compressed vaporized refrigerant is discharged from the compressor 61 through a conduit 66 and passes therethrough to an air cooled finned coil condenser 69. The compressed refrigerant passing through the condenser 69 is cooled and liquefied by the cooling air circulated over the surfaces of the condenser by a fan 70 driven by the compressor driving motor 62. The refrigerant thus liquefied in the condenser 69 flows therefrom through a conduit 71 and is accumulated in a refrigerant receiver 72. The liquid refrigerant thus accumulated in the receiver 72 passes therefrom to a main supply conduit 73 and then through a branch supply conduit or liquid line 74, as shown in Fig. 3, to the refrigerant evaporator coils 59. The liquid refrigerant supplied to the refrigerant evaporator coils 59 is vaporized by the absorption of heat from the contents of the molds 33. This vaporized refrigerant then flows through a branch suction conduit 75, as best shown in Fig. 3, to the main suction conduit 76 through which it is returned to the compressor 61.

The portions of the conduits 73 and 76 which extend along the rear wall of the outer cabinet shell 10 are covered by a protective sleeve 77, preferably molded thereon and made of soft

rubber. It will be noted that the conduits 73 and 76 pass through rubber bushings 78 and 79 positioned in holes formed in a flat rectangular plate 80 which forms the top inner wall of the compartment 16. The plate 80 is a part of the removable top of the cabinet which also includes a rectangular cover plate 81 and heat insulation 82, which is arranged between the plates 80 and 81. A rectangular rubber gasket 83 is positioned on the top of the upstanding flange 11 formed on the outer cabinet shell 10 and extends completely about the same. The cover plate 81 of the removable top of the cabinet rests on a gasket 83 and thus forms a tight seal therewith.

I have provided an arrangement for ejecting the ice, or other material, frozen in the molds 33. This arrangement includes a series of disc-shaped ejecting pistons 84 which are movable into and out of the molds. As best shown in Figs. 6 and 7, the ejecting pistons 84 extend substantially across the bottoms of the molds 33. Each of the pistons 84 is provided with a depending cylindrical extension 85 having a tapped hole formed therein in which the upper end of a vertical actuating link 86 threaded. A disc-shaped soft metal sealing gasket 87 of good thermal conductivity having an upwardly extending peripheral flange 88 is positioned on the lower side of each of the pistons 84 and is held in position by bushings 89. The bushings 89 are in turn held in position by washers 90 and nuts 91, the nuts 91 being threaded on the upper ends of the links 86. The pistons 84 are moved upwardly into the molds 33 by a suitable operating mechanism 35 hereinafter described which includes the links 86, thus ejecting the ice from the interior of the molds 33. I have found, however, that when ice, or similar material, is frozen in the molds 33, it adheres very tightly to the walls of the mold and that consequently an extremely high pressure must be utilized to eject the frozen material from the molds unless some provision is made for melting the frozen bond between the walls of the molds and the material frozen therein.

I have provided an arrangement for heating the walls of the molds 33 in order to melt the frozen bond between the inner surfaces of the walls of the molds and the material frozen therein. This heating arrangement includes a sinusoidal electric heating element 92 which is arranged in close thermal conducting contact with the lower portions of the exterior walls of the molds 33, as best shown in Figs. 6 and 7. The electric heating coil of element 92 includes a high resistance centrally located electric conductor 93 provided with a covering of electric insulation 94 and an outer cover 95 made of material having a high thermal conductivity such as metal.

Water to be frozen is supplied to the refrigerating machine through a conduit or pipe 96 extending through the rear wall of the cabinet and connected to an ordinary water supply system, or other suitable source of water. The water is supplied to the freezing molds 33 of the refrigerating machine from the main supply conduit 96 through a liquid measuring arrangement which supplies just sufficient water to the molds 33 substantially to fill the same during each cycle of operation of the machine.

As shown in Figs. 1 to 4 inclusive, water is supplied through the pipe 96 to a rectangular supply tank 97 which is supported above the banks of molds 30 and 31 on the inwardly extending upper portions 48 of the angle irons 42. The upper portions 48 of the angle irons 42 are

welded, or otherwise rigidly secured, to the rear wall of the tank 97.

I have provided an arrangement for maintaining the water 98 in the supply tank 97 at a substantially constant level which includes a float 99. One end of the float 99 is provided with an extension 100 which is pivotally connected to a bracket 101 formed on the inner side wall of the tank 97 by pivot pin 102. The extension 100 formed on the float 99 is provided with an upwardly extending portion, or lever arm, 103 which actuates a horizontal slidable rod 104. As shown in Fig. 4, a pin 105 is threaded in a suitable tapped hole formed adjacent the top of the lever arm 103 and the position of the pin 105 with respect to the end of the rod 104 may thus be varied by screwing the pin 105 into or out of the hole formed in the lever 103. When the water 98 rises in the tank 97, the float 99 is also lifted and the lever 103 is rotated in a counterclockwise direction about the pivot pin 102, thus bringing the pin 105 into contact with the end of the slidable rod 104 and forcing the rod 104 outwardly. Since the pin 105 may be moved toward or away from the end of the rod 104, the level of the water 98 in the tank 97 at which the rod 104 is pushed outwardly may also be varied.

As shown in Fig. 3, a bridging member 106 having contacts 107 and 108 secured to the opposite ends thereof is mounted on the outer end of the rod 104. The contacts 107 and 108 cooperate with a pair of fixed contacts 109 and 110 to open and close the supply circuit of an energizing coil 111 of an electrically controlled valve 112 located in the water supply conduit 96. The electrically operated valve 112 is of the conventional solenoid type and includes a valve element which is connected to a magnetic armature controlled by the energizing coil 111. The valve element is normally biased to the closed position, thus cutting off the flow of water through the conduit 96.

When the level of the water 98 in the tank 97 decreases, the float 99 moves downwardly, thus rotating the lever 103 in a clockwise direction. A biasing spring, not shown, may be provided on the rod 104 which causes it to be moved to the right, that is, in a direction to close the contacts 108 and 110, as well as the contacts 107 and 109, when the pressure exerted by the pin 105 is released. When these contacts are so closed by the release of the pressure of the lever 103, acting through pin 105, on the rod 104, the circuit is completed from an electric supply line 113 through conductor 114, contacts 108 and 110, bridging member 106, contacts 107 and 109, and conductor 115 to the energizing winding 111. The opposite end of the winding 111 is connected to an electric supply line 116 through a conductor 117. When the coil 111 is thus energized, an armature attached to the valve element of the valve 112 is moved upwardly and the valve element is moved to its open position, thus allowing water to flow through the valve 112 into the tank 97. Water continues to flow into the tank 97 until the float 99 is again moved upwardly to a position in which the rod 104 is pushed outwardly thus opening the contacts 108-110 and 107-109 and so deenergizing the coil 111 and closing the valve 112. It will thus be seen that by means of the arrangement described above the water 98 is maintained at a constant level within the tank 97.

Four substantially identical fluid measuring

vessels 118, 119, 120, and 121, are arranged on the lower side of the tank 97. The measuring vessels are cup-shaped in form and the side walls thereof are substantially cylindrical. As best shown in Fig. 4, upwardly extending cylindrical depressions 122 and 123 are formed in the bottom wall of the tank 97 and the upper edges of the measuring vessels 118 and 119 are closely fitted within the walls of the depressions 122 and 123. Similar depressions are formed in the bottom wall of the tank 97 in which the upper edges of the measuring vessels 120 and 121 are secured. The adjacent portions of the measuring vessels 118 and 119 are welded to the bottom wall of the tank 97, as indicated at 124 and 125, respectively, thus forming fluid-tight seals about the upper edges of the fluid measuring vessels. Holes 126 and 127 are formed in the bottom wall of the tank 97 at the centers of the depressions 122 and 123. Hollow internally threaded bushings 128 and 129 are mounted in the holes 126 and 127, respectively, and the sides of the bushings are welded to the edges of the holes, as indicated at 130 and 131, respectively.

A tubular two-part valve casing is mounted in each of the fluid measuring vessels. The valve casings for the measuring vessels 118 and 119 include complementary cylindrical cup-shaped upper and lower portions 132 and 133, respectively. The upper and lower portions of the valve casings are secured together by a threaded internal sleeve 134. The bottom wall of the lower portion 133 of each valve casing is provided with an outlet opening 135 therein which is surrounded by an annular upstanding valve seat 136. The outlet opening 135 registers with a centrally located bore formed in a bushing 137 which is mounted in an aperture 138 formed in the bottom of the measuring vessel. The edge of the aperture 138 is welded to the bushing 137, as indicated at 139, thus forming a tight seal therewith. The upper side of the bushing 137 is provided with a counterbore 140 which is adapted to receive the lower end of the valve casing and a sealing gasket 141 is positioned in the counterbore 140 in order to prevent the leakage of fluid between the adjacent surfaces of the lower portion 133 of the valve casing and the bushing 137. A similar gasket 142 is positioned on the upper side of the top wall of the portion of the valve casing 132 and is pressed thereon by a ring 143 threaded in a tapped counterbore 144 formed in the top of the bushing 128. It will be noted that the upper portion 132 of the valve casing is provided with an inlet opening 145 in the top wall thereof, the lower end of which is surrounded by an annular inwardly extending valve seat 146.

The measuring vessels 118, 119, 120, and 121 are provided with valve actuating rods 147, 148, 149, and 150, respectively. A disc-shaped outlet valve 151 is secured to the lower end of the actuating rod 147 of the measuring vessel 118 and a similar disc-shaped outlet valve 152 is secured to the lower end of the actuating rod 148 of the measuring vessel 119. Soft rubber sealing discs 151a and 152a are secured to the lower sides of the outlet valves 151 and 152, respectively. Similarly, duplicate disc-shaped inlet valves 153 and 154 are slidably mounted on the actuating rods 147 and 148, respectively, and have soft rubber sealing discs 155 and 156 positioned on the upper surfaces thereof. Compression springs 157 and 158 surround the actuating rods 147 and 148 and bear against the inner sides of the adjacent inlet and outlet valve elements. The upper por-

tions 132 of the valve casings are provided with ports 159 in the side walls thereof and the lower portions 133 of the valve casings are provided with similar ports 160 in the side walls thereof.

It will thus be seen that when the actuating rods are moved to their extreme upper position, which is the position of the actuating rod 147 illustrated in Fig. 4, that the compression spring 157 is compressed between the outlet valve element 151 and the inlet valve element 153, thus pressing the sealing disc 158 tightly against the inlet valve seat 146 and closing the inlet passage 145. At the same time, the outlet valve element 151 is moved upwardly away from its cooperating seat 136 and any fluid contained in the measuring vessel 118 flows therefrom through the ports 160 and outlet opening 135 into a branch of conduit 161 which is secured to the bushing 137.

Similarly, when one of the actuating rods is pushed downwardly to its extreme lower position, which is the position of the actuating rod 148 shown in Fig. 4, the sealing disc 152a of the outlet valve 152 is pressed tightly against the valve seat 136 and prevents any fluid in the measuring vessel 118 from flowing out through the outlet opening 135. At the same time, the inlet valve 154 is moved downwardly away from its cooperating sealing seat 159 and water, or other fluid, within the supply tank 97 flows into measuring vessel 119 through the inlet opening 145 and ports 159. It will thus be seen that the compression springs 157 and 158 serve to hold the valve elements tightly against their cooperating valve seats when in the closed position and even though the valve seats or valve elements become worn through continued use, sealing of the inlet and outlet openings will be unimpaired.

The entire valve assembly for any one of the measuring vessels may be readily disassembled for purposes of inspection and repair by unscrewing the ring 143 and then lifting the tubular valve casing and valve elements contained therein upwardly through the central bore formed in the hollow bushing 128, since the diameter of the portions 132 and 133 of the valve casing is slightly less than the diameter of the bore in the bushing 128.

The measuring vessels 118, 119, 120, and 121 are designed with such dimensions that each of them will hold a volume of liquid above the lower edge of the ports 160 thereof, just sufficient to fill all of the freezing molds 33 in one of the banks of molds 30 or 31. I have arranged the measuring vessels in pairs and the measuring vessels 118 and 119 supply water, or other liquid, to the freezing molds 33 in the bank of molds 30 through branch outlet conduits 161 and 162 which are connected by a T-connection 163 to a main conduit 164. The lower end 165 of the conduit 164 extends over the depression 36 formed in the cover plate 35 of the bank of molds 30 and consequently water discharged from the lower end 165 of the conduit 164 is distributed through the notches 37 to all of the molds 33 in the bank of molds 30. Similarly, the other pair of measuring vessels 120 and 121 is provided with branch outlet conduits 166 and 167 which communicate through a T-connection 168 with a main conduit 169. The lower end 170 of the conduit 169 extends over the depression 36 formed in the cover plate 35 of the bank of molds 31. Thus, water discharged from the lower end 170 of the conduit 169 is distributed through the notches 37 to all of the molds 33 in the bank of molds 31.

I have provided an arrangement for operating the inlet and outlet valves of the measuring vessels in such manner that one of the measuring vessels in each pair of them is being filled with water at the same time that water is being discharged or permitted to flow from the other of the measuring vessels to the molds which they supply. For example, the inlet valve 154 of the measuring vessel 119 is opened, thus admitting water to the interior of the measuring vessel 119 and filling the same, at the same time that the outlet valve 151 of the measuring vessel 118 is opened, thus allowing the water contained in the measuring vessel 118 to flow through the conduits 161 and 164 to the bank of molds 30. The valve operating arrangement is also designed so that both of the banks of molds 30 and 31 will be filled with water at the same time. Consequently, the outlet valve of the measuring vessel 120 is opened at the same time that the outlet valve of the measuring vessel 118 is opened and the water contained in the measuring vessel 120 flows through the conduits 166 and 169 to the bank of molds 31. When the outlet valve of the measuring vessel 120 is opened, the inlet valve of the measuring vessel 121 is opened and the outlet valve thereof is closed, so that the measuring vessel 121 is filled with water from the supply tank 97 while the measuring vessel 120 is being emptied.

Each of the measuring vessels 118, 119, 120 and 121 is provided with a vent tube 309 extending upwardly from the upper portion of the measuring vessel, through the upwardly directed depressions in the bottom of tank 97 into the upper portion of tank 97 above the level of the liquid 98. By this means, trapping of air within the measuring vessels is provided against and the measuring vessel may be filled more readily.

The mechanism which I have provided for opening and closing the inlet and outlet valves of the measuring vessels 118, 119, 120, and 121, includes a pair of oscillating arms 171 and 172 which are loosely journaled on a horizontal shaft 173. Forked ends 174 and 175 are provided on the operating arm 171 and slidably engage the valve actuating rods 147 and 148, respectively. Similar forked ends 176 and 177 are provided at the opposite ends of the arm 172 and slidably engage the valve actuating rods 149 and 150. As best shown in Fig. 4, a pair of nuts 178 is threaded on the upper end of the valve actuating rod 147 and form a stop thereon, which is engaged by the forked end 174 of the arm 171. Thus, when the arm 171 is rotated in a clockwise direction, the forked end 174 thereof engages the lower nuts 178 and lifts the valve actuating rod 147 upwardly until the inlet valve 153 is moved to its closed position, and the outlet valve 151 is moved to its open position. Collars 179 are positioned on the upper ends of sleeves 180 which surround the valve actuating rods 147 and 148 and form a lower stop for the forked ends 174 and 175 of the actuating arm 171. The sleeves 180 are slidably mounted on the valve actuating rods 147 and 148 and the lower ends of the sleeves are rigidly secured to the inlet valve elements 153 and 154. Consequently, when the arm 171 is oscillated in a counterclockwise direction, the forked end 174 thereof pushes down on the collar 179 and sleeve 180. As a result, the spring 157 is compressed and the outlet valve element 151 is forced down to its closed position against the seat 136. At the same time, the inlet valve

element 153 is moved downwardly to its open position. Nuts 178 are also provided on the upper ends of the valve actuating rods 149 and 150, forming upper stops thereon and collars 179 and sleeves 180 are also positioned on these valve actuating rods to form lower stops thereon.

The operating arms 171 and 172 are oscillated by a horizontal rod 181 having its opposite ends positioned in longitudinal slots 182 and 183 formed in the arms 171 and 172, respectively. The rod 181 is eccentrically mounted on a pinion 184 and is rotated thereby. The pinion 184 meshes with a gear wheel 185 of comparatively large diameter, which is rigidly mounted on the horizontal shaft 173. As best shown in Fig. 5, the horizontal shaft 173 is provided with a pair of sleeves 186 and 187 which are journaled in inverted L-shaped brackets 188 and 189, respectively. The upper ends of the brackets 188 and 189 are welded, or otherwise rigidly secured, to a horizontal bracket 190 of inverted U-shape having its opposite ends secured to the side wall of the supply tank 97 by bolts 191.

A ratchet and pawl arrangement has been provided for rotating the shaft 173, which includes a ratchet wheel 192 rigidly secured to the shaft 173 and an actuating pawl 193. The lower end of the pawl 193 is pivotally connected by a pivot pin 194 to a link 195 having its opposite end journaled on the shaft 173. The pivot pin 194 also pivotally connects the upper end of the vertical rod 196 with the pawl 193. It will be noted that the rod 196 extends through an aperture formed in the bottom of the supply tank 97 and a sleeve 197 is provided which surrounds the aperture formed in the tank and extends above the normal level of the water 98 therein.

When the rod 196 moves downwardly, the pawl 193 is also moved downwardly and causes the ratchet 192 to rotate in a clockwise direction due to its engagement with one of the teeth of the ratchet 192. As a consequence, the shaft 173 and gear wheel 185 are also rotated in a clockwise direction, and since the pinion 184 meshes with the gear wheel 185, the pinion is rotated in a counterclockwise direction. This counterclockwise rotation of the pinion 184 causes the rod 181 to be moved in a counterclockwise direction and the operating arms 171 and 172 are also moved in a counterclockwise direction. When the rod 196 is moved upwardly again, the pawl 193 engages the next tooth on the ratchet 192 and upon a second downward movement of the rod 196 the clockwise rotation of the gear 185 and counterclockwise rotation of the pinion 184 will be continued. The gear ratios of the pinion 184 and gear 185 are so related that one actuation of the ratchet 192 will cause the pinion 184 to be rotated through substantially 180 degrees. The rod 181 will be moved upwardly upon the second actuation of the ratchet and pawl mechanism and the arms 171 and 172 will thus be moved in a clockwise direction, to the position shown in Figs. 3 and 4.

The mechanism for moving the ratchet actuating rod 196 and the actuating links 86 of the ejecting pistons 84 are mechanically interconnected in such manner that the rod 196 and links 86 are moved in a predetermined sequential relation. The mechanism for ejecting blocks of ice from the molds 33 is thus mechanically interlocked in such a manner with the mechanism for supplying water to the molds that a fresh supply of water cannot pass to the molds 33 to replenish the contents thereof before the ejecting pistons 75

84 have been actuated to eject previously frozen ice therefrom.

In the machine illustrated, the lower ends of the actuating links 86 are pivotally connected by pins 198 and 199 for the banks of molds 30 and 31, respectively, to U-shaped brackets 200 and 201. The brackets 200 and 201 are in turn rigidly secured to channel-shaped bars 202 and 203, respectively. The front sides of two U-shaped frames 204 and 205 are formed by the bars 202 and 203, the sides thereof being formed by channel-shaped bars 206 and 207, respectively. The U-shaped frames 204 and 205 are connected by channel-shaped links 208 which are pivotally connected at their opposite ends by bolts 209 and 210 to approximately the midpoints of the side bars 206 and 207 of the frames 204 and 205, respectively. The frame 204 is supported at its rear edge by a pair of pivots 211 journaled in the vertical bars 42 of the machine supporting frame. Similarly, the rear edge of the frame 205 is supported by a pair of pivots 212 which are also journaled in the support 42. The links 208 are connected by an X-shaped frame made up of bars 213 and 214 having their opposite ends rigidly secured to the ends of the links 208. The crossed center portions of the bars 213 and 214 are secured together by a pin 215 extending therethrough. Since the side bars 206 of the frame 204 are shorter than the side bars 207 of the frame 205, the frame 204 is tilted downwardly toward the frame 205. Consequently the pistons 84 in each bank of molds 30 and 31 will be moved substantially the same linear distance even though the links 208 are closer to the pivots 211 than to the pivots 212.

The X-shaped frame made up of the bars 213 and 214 is moved upwardly by a solenoid operated actuating mechanism and this upward movement of the bars 213 and 214 swings the U-shaped frames 204 and 205 upwardly, thus moving the ejecting pistons 84 upwardly to the upper ends of the molds 33 due to the movement of the actuating links 86. The solenoid actuating mechanism includes an energizing coil 216 which surrounds a vertically movable magnetic armature 217. A yoke 218 having an inverted U-shape is secured to the lower end of the armature 217. The lower ends of the yoke 218 are slidably mounted in cylindrical hollow guides 219 and 220 which are secured at their lower ends to the bars 213 and 214 by rivets 221 and 222, respectively. The upper end of a tension spring 223 is secured to the top of the yoke 218 and the lower end of the spring is secured to the pin 215. I have found it desirable to use such a spring and yoke arrangement to connect the armature 217 of the solenoid operating mechanism and the linkage which is moved thereby in order that the ejecting pistons 84 may be moved upwardly into the molds 33 at a relatively slow rate of speed as compared to the sharp upward movement of the solenoid armature 217 when the coil 216 is energized. It is desirable to move the pistons 84 at a comparatively slower speed because of the resistance offered thereto by the ice in the molds and also because the comparatively large inertia of the linkage mechanism which connects the pistons 84 and the solenoid operating mechanism would otherwise impose a very heavy load on the solenoid if the entire linkage mechanism was given a sudden sharp movement. The yoke and spring arrangement which I have provided results in the desired difference in speed of movement of

the various parts since when the coil 216 is energized, the tension spring 223 allows the armature 217 and yoke 218 to move upwardly with the sharp sudden movement without imparting any substantial movement to the linkage mechanism connecting the pistons 84 thereto. Such a movement of the yoke 218 and armature 217 places the spring 223 under tension, however, and thus stores potential energy therein. The tension in the spring 223 causes the X-shaped frame made up of the bars 213 and 214 to move upwardly at a comparatively slow rate of speed and the frames 204 and 205 are similarly swung upwardly about their pivots 211 and 212. As a consequence, the pistons 84 are moved slowly upwardly in the molds 33 by the actuating links 96. The upward movement of the bars 213 and 214 continues until the lower ends of the yoke 218 strike the bottoms of the guides 219 and 220, thus limiting the upward movement of the pistons 84.

The ratchet actuating rod 196 is connected at its lower end to the bar 214 by a pin 196A. Consequently when the bar 214 and the remainder of the linkage for operating the ejecting pistons 84 is moved upwardly the rod 196 is also moved upwardly and causes the pawl 193 to engage the next adjacent tooth on the ratchet 192. The ratchet 192 is not moved and consequently the valves of the measuring vessels are not moved, however, until the rod 196 is again moved downwardly by the actuating linkage of the pistons 84. When the rod 196 is again so moved downward two of the measuring vessels are emptied into the banks of molds 30 and 31 but at the same time the pistons 84 are retracted, the previously frozen blocks of ice having already been ejected from the molds. It will thus be seen that this mechanical interconnection of the valve actuating mechanism for the measuring vessels and the piston actuating mechanism insures a sequential series of operations in which the previously frozen ice is always first ejected from the molds before more water is supplied thereto.

When blocks of ice, or other frozen material, are ejected from the freezing molds 33 by the upward movement of the pistons 84, the blocks move vertically upward out of the molds until they strike angularly disposed deflecting plates 224 and 225 which are arranged above the banks of freezing molds 30 and 31, respectively. The deflecting plates 224 and 225 are substantially rectangular in shape and the rear edges thereof are folded over longitudinally extending rods 226 and 227, the opposite ends of which are journaled in suitable holes formed in the side plates 41. Tension springs 228 and 229 are secured to the deflecting plates 224 and 225, respectively, the opposite ends of the tension springs being secured to adjacent portions of the side plates 41. The deflecting plates 224 and 225 are retained at an angle over the tops of the freezing molds by stops 224a and 225a. The blocks of ice striking the deflecting plates 224 and 225 tend to rotate the same backwardly away from the tops of the banks of molds, thus placing the springs 228 and 229 under tension. When the blocks of ice have finally moved upwardly a sufficient distance to be free of the molds 33, the tension springs 228 and 229 tend to pull the deflecting plates 224 and 225 back to their original positions against their stops, thus pushing the blocks of ice off of the tops of the banks of freezing molds 30 and 31. The blocks of ice then fall into a drawer 230 which is located in the bottom of the compartment

15 in alignment with the door-opening 18 through which it is readily accessible. The front edge of the drawer 230 is provided with a deflecting plate 231 which extends upwardly and outwardly therefrom and directs the falling blocks of ice into the drawer where they are stored until it is desired to use them.

I have made provision for preventing the subsequent melting of the blocks of ice stored in the drawer 230 if they are left there for some time before being used. In the machine illustrated, a sinuous dry type evaporator conduit 232 is mounted on the upper surface of the plate 52 directly above the drawer 230. The evaporator coil 232 is preferably brazed, or otherwise rigidly secured, to the plate 51 in good heat exchange relationship therewith. Liquid vaporizable refrigerant passes to the evaporator coil 232 through a branch conduit 233 which communicates with the main refrigerant conduit 13. The liquid refrigerant passing through the evaporator conduit 232 is vaporized by the absorption of heat from the interior of the compartment 15 and the refrigerant thus vaporized returns through a branch discharge conduit 234 to the main discharge or suction conduit 16.

I have provided automatic thermostatic expansion valves 235 and 236 for maintaining the differences in pressure between the inlets and outlets of the evaporators 59 and 232 at substantially constant values. The thermostatic expansion valve 235 is located in the branch supply conduit 14 of the evaporator 59 and the thermostatic expansion valve 236 is located in the branch supply conduit 233 of the evaporator 232. The automatic thermostatic expansion valves 235 and 236 are of the conventional type and include bulbs 237 and 238, respectively, which are connected thereto by conduits 239 and 240. The bulbs 237 and 238 contain a fluid, such as sulphur dioxide, which is cooled by the portions of the discharge conduits 15 and 234 with which they are arranged in good thermal contact. A bellows, or similar pressure responsive member, is included in each of the thermostatic expansion valves and is subjected to the pressure of the refrigerant entering the evaporator on one side and to the pressure of the fluid in the bulb associated with the valve on the other side. When the pressure differential prevailing between the inlet and outlet of one of the evaporators decreases, the bellows of its associated thermostatic expansion valve moves to open the valve and admit refrigerant to the evaporator and as the pressure differential increases, the bellows, or the like, gradually moves to close the valve, thus cutting off the supply of liquid refrigerant to the evaporator, this action being modified by the thermostatic elements 237 and 238 respectively.

It is unnecessary to maintain the temperature of the evaporator 232 at as low a temperature as evaporator 59 since the ice within drawer 230 can be kept from melting at a higher temperature than prevails in the freezing molds. Accordingly, I place a pressure valve 310 in conduit 234 so adjusted that it will close when the pressure within evaporator 232 reaches a predetermined minimum. Therefore the pressure within evaporator 232 will not be reduced below the predetermined minimum even though the pressure within evaporator 59 is much lower than this minimum.

The control arrangement which I have provided for the refrigerating machine described above serves automatically to control the operation

thereof and particularly to meet various requirements of the user. It is desirable that the machine should be selectively operable either continuously to freeze quantities of ice, or on the other hand, simply to store ice which has already been made and prevent its melting. For this requirement of dual operation, I have provided a control mechanism which includes a manually operable two-position switch having a movable switch arm 241 and two stationary contacts 242 and 243, as shown in Fig. 3. When the switch arm 241 is moved into its left-hand position into contact with the stationary contact 242, the supply of refrigerant to the evaporator coils 59 of the freezing molds 33 remains cut off, because the operating coil 244 is not energized and the solenoid operated valve 245 located in the branch supply conduit 74 is biased to its closed position when deenergized. At the same time, refrigerant is supplied to the evaporator coil 232 through the branch supply conduit 233 from the refrigerant liquefying unit 32. The operation of the compressor 61 and its driving motor 62 is in such case controlled by switch 246 having a pair of fixed contacts 247 and 248 closed by a movable bridging member 249, which is actuated by a thermally responsive element, such as a bellows 250. This bellows is connected through a conduit 251 with a thermostatic bulb 252 arranged in heat exchange relationship with the evaporator 232. The bulb 252 contains an elastic fluid such as sulphur dioxide and when the evaporator 232 reaches a predetermined high temperature, the fluid in the bulb 252 expands and causes a consequent expansion of the bellows 250. This results in a closing of the contacts 247 and 248 by the movable bridging member 249, thus completing an electrical supply circuit for the motor 62 from the electric supply line 113 through a conductor 253, switch arm 241 and contact 242, conductor 254, contacts 247 and 248, bridging member 249, conductor 255, and conductor 256. The motor 62 is connected to the other supply line 116 through conductors 257 and 258. When the evaporator 232 reaches a predetermined low temperature, the bellows 250 contracts and moves the bridging member 249 out of contact with the contacts 247 and 248. The supply of current to the motor 62 is consequently cut off and the compressor 61 is stopped. The evaporator 232 is operated within a sufficiently low temperature range to cool the compartment 15 and prevent the melting of ice stored in the drawer 230 even when ice is not being frozen in the molds 33.

On the other hand, when the switch arm 241 is moved to the right into contact with the stationary contact 243, a control circuit is set up for operating the machine continuously and automatically to freeze successive quantities of ice, or the like. In such case, the molds 33 are filled with water from an ordinary city supply which is, of course, comparatively warm. Consequently, a fluid, such as sulphur dioxide, which is contained in a thermostatic bulb 259, is caused to expand and the pressure of this expansion is transmitted through a conduit 260 and a bellows 261 connected thereto is also caused to expand. It should be noted that bulb 259 is located in heat exchange relation with one of the molds 33 and the movement of the bellows 261 is thus responsive to the temperature of the contents of the mold. The expansion of the bellows 261 causes a rod or operating member 262, which is rigidly

connected thereto, to be moved to the right. Two contact closing bridging members 263 and 264 are carried by the rod 262 being insulated therefrom. The bridging member 264 is rigidly secured to the rod 262, while the bridging member 263 is slidably mounted thereon and biased to a predetermined position on the rod 262 by a compression spring 265. When the rod 262 has completed its movement to the right upon expansion of the bellows 261, it is held in that position by a fixed permanent magnet 266 which exerts a magnetic attraction on an armature 267 secured to the outer end of the rod 262. Also, the contact bridging member 264 closes contacts 268 and 269, 15 while the contact bridging member 263 closes the contacts 270 and 271.

The closing of the contact 243 by the switch arm 241 completes the electric supply circuit for an energizing winding 272 of a normally open electrical contactor 273. Current is supplied to the winding 272 from the electric supply line 113 through the conductor 253, switch arm 241, contact 243, conductor 274, and conductor 275. The other end of the energizing coil 272 is connected to the other electric supply line 116 through conductor 258. The energizing coil 272 is thus supplied with current upon the closing of contact 243 by switch arm 241 and the contactor 273 closes, thus placing its contact bridging member 276 in contact with stationary contacts 277, 278, and 279. Upon the closing of the contactor 273, the supply circuit of the compressor driving motor 62 is completed from the electric supply line 113 through conductor 253, switch arm 241, contact 243, conductor 280, contact 279, contact bridging member 276, contact 278, conductor 281, contacts 268 and 269, contact bridging member 264, and conductors 282, 283 and 256. It will be noted that the other side of motor 62 is permanently connected to the current supply line 116 through conductors 257 and 258. The electric driving motor 62 is thus started and refrigerant is compressed in the compressor 61 and liquefied in the condenser 69. Upon the closing of contact 243 by switch arm 241 current is also supplied to the energizing winding 244 of refrigerant solenoid valve 245 from the electric supply line 113 through conductor 253, switch arm 241, contact 243, conductor 274 and conductor 244a. The other side of the winding 244 is permanently connected to the other electric supply line 116 through conductors 244b and 258. When the winding 244 is thus energized the normally closed valve 245 is opened and liquid refrigerant is admitted to the evaporator coils 59 through the branch supply conduit 74 thus cooling the contents of the molds 33. It will be noted that liquid refrigerant is also simultaneously supplied to the evaporator 232 so that the interior of the compartment 15 is cooled to a temperature below 32° F. in order to prevent the melting of ice stored in the compartment. Liquid refrigerant is continuously supplied to the evaporator cooling coils 59 of the freezing molds 33 until the water in the molds is frozen. Upon the freezing of the ice in the molds 33, the temperature of the bulb 259 reaches a predetermined low value, preferably about -3° F. and the pressure of the fluid contained in the bulb 259 and bellows 261 is, of course, correspondingly reduced. The operating rod 262 is moved to the left to the position in which the contact bridging members 263 and 264 are in their open position when the pressure of the fluid in the bellows 261 reaches a predetermined low value which is sufficiently small that

the magnetic force exerted by the magnet 266 on the armature or bar 267 is overcome. When such a predetermined low value of pressure is reached, the operating rod 262 moves rapidly to the left as the bellows 261 contracts and the supply of current to the compressor driving motor 62 is cut off by the opening of the contacts 268 and 269 in its supply circuit.

When the contacts 268 and 269 are closed by the contact bridging member 264, the energizing winding 284 of a normally closed contactor 285 is supplied with current from the electric supply line 113 through conductor 253, switch arm 241, contact 243, conductor 280, contacts 279 and 278, conductor 281, contacts 268 and 269, and conductor 282. The other side of the energizing winding 284 of the contactor 285 is connected to the other supply line 116 through conductors 286 and 258. When the energizing winding 284 is so supplied with current, the contact bridging member 287 is moved upwardly to its open position. The contacts 288 and 289 are opened when the ice is frozen in the molds 33 and the contactor 285 is deenergized so that its contacts 288 and 289 are closed by the contact bridging member 287. Upon the closing of contacts 288 and 289, current is supplied to the electric heating element 92 surrounding the freezing molds 33 from the electric supply line 113 through conductor 253, switch arm 241, contact 243, conductor 280, contacts 277 and 279, bridging member 276, conductor 290, contacts 288 and 289, bridging member 287, conductor 291, and branch conductors 292 and 293. The electric heating elements 92 are also connected to the other electric supply line 116 through branch conductors 294 and 295, conductor 296 and conductor 258. It will be noted that the heating elements 92 for each of the banks of molds 30 and 31 are connected in parallel relation to conductors 291 and 296 by branch conductors 292, 293, 294 and 295.

As the electric heating elements 92 are heated by the electric current supplied thereto, this heat is transmitted to the walls of the freezing molds 32 with which the heating elements 92 are in direct contact. The frozen bond between the walls of the molds 33 and the blocks of ice contained therein is consequently melted, so that the blocks of ice may be readily ejected from the molds. As the molds 33 are warmed by the heating elements 92, the fluid in the thermostatic bulb 259 is also warmed and causes a consequent expansion of the bellows 261. This expansion of the bellows 261 moves the operating rod 262 gradually to the right. It will be noted that the contact bridging member 263 is located closer to its cooperating contacts 270 and 271 than is the contact bridging member 264 to its cooperating contacts 268 and 269. Consequently, as the operating rod 262 moves to the right, the contacts 270 and 271 are closed by the contact bridging member 263 before the contacts 268 and 269 are closed. Upon the closing of the contacts 270 and 271, current is supplied to an energizing winding 297 of a normally open electrical contactor 298. Current is supplied to the energizing winding 297 from electric supply line 113 through conductor 283, switch arm 241, contact 243, conductor 280, contacts 279 and 277, conductor 290, contacts 288 and 289, conductor 291, conductor 293, contacts 270 and 271, and conductor 300. The other side of the energizing winding 297 is connected to the other electric supply line 116 through conductors 301 and 302. Upon the energization of contactor 298, its contact bridging member 303 is moved

upwardly into contact with stationary contacts 304 and 305. Upon such closing of the contactor 298, current is supplied to the solenoid winding 216 from the electric supply line 113 through conductor 253, switch arm 241, contact 243, conductor 280, contacts 277 and 279, conductor 290, contacts 288 and 289, conductor 291, conductor 306, contacts 304 and 305, and conductor 307. The other side of the winding 216 is connected to the other electric supply line 116 through conductors 308 and 302.

Upon the energization of winding 216, the armature 211 of the solenoid operating mechanism is moved upwardly, thus placing the spring 223 under tension. This tension of the spring 223 causes the X-shaped frame made up of the bars 213 and 214 to be pulled upwardly, swinging the U-shaped frames 204 and 205 upwardly about their pivots 211 and 212. Consequently, actuating links 86 move the ejecting pistons 84 upwardly adjacent the tops of the freezing molds 33 and force the blocks of ice out of the molds. The blocks of ice thus forced out of the molds 33 are pushed from the tops of the banks of molds 30 and 31 by the deflector plates 224 and 225 and fall into the storage drawer 230.

The continued heating of the molds 33 by the electric heating elements 92 causes the pressure of the fluid in the bulb 259 and bellows 261 to increase until the operating rod 262 is moved to the right a sufficient distance that the contact bridging member 264 also closes the contacts 268 and 269. Upon the closing of the contacts 268 and 269, the contactor 285 is energized, current being supplied to its energizing winding 284 from the electric supply line 113 through conductor 253, switch arm 241, conductor 280, contacts 278 and 279, conductor 281, contacts 268 and 269, and conductor 282. The other side of the energizing winding 284 is connected to the other supply line 116 through conductors 286 and 258. Upon such energization of the contactor 285, its contact bridging member 287 is moved upwardly to the open position, thus cutting off the supply of current to the heating elements 92 and to the solenoid contactor 298. Upon the deenergization of the contactor 298, the solenoid coil 216 is deenergized by the opening of contacts 304 and 305 so that the armature 211, yoke 218, and the linkage mechanism which connects the armature 211 and ejecting pistons 84 is allowed to return to its normal lower position due to gravity.

The downward movement of the bar 214 also causes the rod 196 to be moved downwardly, which in turn causes the pawl 193 to move the ratchet 192 in a clockwise direction. When the ratchet 192 is moved in a clockwise direction, the arms 171 and 172 are swung from the position shown in Fig. 4 in a counterclockwise direction, thus opening the outlet valves 152 of measuring vessels 119 and 121 and closing the inlet valves 154 thereof. Water thus flows from the measuring vessels 119 and 121 through the conduits 162-164 and 167-168 to the banks of molds 30 and 31, respectively, where it is distributed to the freezing molds 33 and fills the same. At the same time, the counterclockwise movement of the operating arms 171 and 172 causes the inlet valves 153 of the measuring vessels 118 and 120 to be opened and the outlet valves 151 thereof to be closed. Upon such opening of the inlet valves of the measuring vessels 118 and 120, water flows therethrough from the supply tank 97 and fills the same. It will thus be seen that the measuring vessels 118 and 120

are filled with water in preparation for the next cycle of operation, while the water previously contained in the measuring vessels 118 and 121 is being discharged into the banks of freezing molds 30 and 31.

The flow of water into the measuring vessels 118 and 120 from the supply tank 97 causes a lowering of the level of the water therein and consequently the float 99 rotates downward in a clockwise direction about its pivot 102 and allows the rod 104 to move to the right, thus closing contacts 109 and 110. Upon the closing of these contacts, current is supplied to the energizing coil 111 of the electrically operated valve 112, causing the same to be opened. When the valve 112 is open, additional water is supplied through the pipe 96 to the supply tank 97 until the level of the water 98 therein again reaches a sufficiently high point that the float 99 is rotated upwardly a sufficient distance in a counter-clockwise direction about its pivot 102 that the rod 104 is again moved to the left and the contacts 109 and 110 opened. When these contacts are opened, the coil 111 is again deenergized and the valve 112 consequently closed.

At the end of the description of the cycle of operation of the control arrangement described above, it was noted that the contact bridging member 264 closes the contacts 268 and 269 when the operating rod 262 had moved to its extreme right-hand position. Upon such closing of the contacts 268 and 269, the compressor driving motor 62 is again energized through the electrical supply circuit described above and the compressor 61 again starts to compress gaseous refrigerant which is liquefied in the condenser 69 and supplied to the evaporator coils 59 of the molds 33. The operating cycle described above is then repeated and continued. During such repetitions of the cycle of operation, blocks of ice are frozen in the molds 33, the molds are then heated until the ice may be readily ejected therefrom, and the pistons 84 then eject the blocks of ice from the molds, after which the molds are again filled with water. It will thus be seen that I have provided an arrangement by means of which blocks of ice of a convenient and usable size are continuously supplied during so long a period as the operator may desire. In the machine illustrated ice is made at the rate of about three and one half pounds per hour when the ambient temperature is about 75° F. Moreover, the machine is entirely self-contained and is mounted in a portable cabinet of reasonably small dimensions so that it may be placed in any desired location in the establishment in which it is used.

After a sufficient number of blocks of ice have been frozen to meet the requirements of the operator, the manually controlled switch arm 241 is moved to the left into contact with the stationary contact 242. The supply of electric current to the energizing coil 244 of the solenoid operated valve 245 is thus cut off and the normally closed valve 245 closes, shutting off the supply of liquid refrigerant to the evaporator cooling coils 59 of the freezing molds 33. At the same time, the compressor 61 and its driving motor 62 are placed under the control of the thermostatically operated switch 246 which operates to maintain the evaporator 232 at a sufficiently low temperature to prevent the melting of blocks of ice stored in the drawer 230, as described above. If the operator desires to shut off the operation of the compressor 61 entirely, the manually con-

trolled switch 256a is opened and the supply of current to the driving motor 62 is thus cut off irrespective of the position of the control switch 241.

5 A modification of my invention is illustrated in Figs. 8 to 13, inclusive. A cabinet structure somewhat similar to that shown in Figs. 1 and 2 is utilized. This cabinet includes an outer rectangular sheet metal shell 312 having a rectangular opening in the top thereof. The refrigerating cabinet is provided with an inner liner 313 also having an open top which covers three sides and the bottom of the cabinet. An aperture or door opening 318 closed by a door 318a, is arranged in the front wall. The outer liner 312 and the inner liner 313 are separated by blocks of heat insulating material 314, for example, wood, and the space between the liners is filled with heat insulation 315. The inner liner 313 is provided with a flanged portion 316 at the top of the inner wall thus defining a rectangular opening 317. In order to close the top of the refrigerator cabinet, I have provided a hood comprising an inner shell 319 and an outer shell 320, separated by blocks of heat insulating material 321, such as wood, the space between the shells being filled with heat insulation 322. The hood rests upon the walls of the cabinet, a strip of flexible material such as rubber being inserted between the hood and cabinet walls to serve as a sealing means.

30 The cabinet described above is provided with a refrigerating machine embodying my invention which includes banks of freezing molds 323 positioned in the refrigerating compartment 15. Liquid to be frozen, such as water, is automatically supplied to the banks of molds 323, frozen, and ejected from the apparatus in a manner similar to that already described. In the modification illustrated in Figs. 8 to 13, inclusive, I have shown two banks of molds, each bank including two rows of vertical cylindrical pockets or molds 324. The upper surface of the banks of molds as well as the interior surface of the 35 pockets or molds is covered with a thin rubber lining 325. The rubber lining 325 extends over the edge of the mold 323 and is fastened to the edge of the mold by means of a retaining strip 326. The rubber lining at the bottom of each 40 cylindrical pocket or mold 324 is provided with a thickened portion 327 which is hollowed out to receive the head 328 of a plunger or push rod 329.

45 The banks of molds 323 are supported within the refrigerating cabinet upon a frame-work. The supporting frame-work comprises vertical channel members 423 at the corners joined at the lower ends by horizontal channel members 424 and at the upper ends by horizontal channel members 425. Flange 342 is suitably fastened as by welding about the upper portion of the above frame-work, the flange 342 being suitably fastened as by nuts and bolts to an inwardly extending flange 343 which rests on blocks 314. 50 The banks of molds 323 are supported in any suitable manner as by screws, for example, from U-shaped channel members 426 which are suitably supported between channel members 423.

55 The contents of the banks 323 are cooled by liquid vaporizable refrigerant circulated through refrigerator evaporator conduits 330 which are cast in the walls of the molds. In order to cool the mold as evenly as possible the evaporator coil 330 is formed as shown in Fig. 12. The first 60 turn of the coil substantially surrounds both

rows of pockets or molds of one bank. Midway across the fourth side, however, the coil is turned inwardly and directed through the bank between the two rows of pockets or molds so that a second loop is arranged in such a way as to surround only one row of pockets or molds. After the second loop is completed, a third loop is made similar to the first, etc. In other words, beginning at the lower left-hand corner in Fig. 12, the coil is formed as follows: back along the left-hand side, across the entire rear end of the bank, up to the front of the bank, across the right-hand half of the front of the bank, backwardly between the two rows of pockets or molds, to the right across the right-hand portion of the bank, up to the front of the bank, entirely across the front of the bank, back along the left-hand side of the bank, to the right across the left-hand portion of the rear of the bank, up to the front between the two rows of pockets or openings, to the left-hand portion of the bank, etc., until the coil is completed.

Liquid refrigerant is supplied to the evaporator coil 330 in the bank of molds 323 from the refrigerant liquefying unit 32 located in the machinery compartment in the lower portion of the refrigerating cabinet. The refrigerant liquefying unit may be the same as the unit described above. The liquid refrigerant which has been accumulated in the liquid receiver 12 passes therefrom through a main supply conduit 331 and then through branch conduits 332 and 333, as best shown in Fig. 10, to the refrigerant evaporator coil 330. Since two banks 323 have been illustrated, a conduit 334 has been provided to join the refrigerating coils 330 so that the two banks are in series relationship. The liquid refrigerant supplied to the refrigerant evaporator coil 330 is vaporized by the absorption of heat from the contents of the molds 324. This vaporized refrigerant then flows through a branch conduit 335 to the main suction conduit 336 through which it is returned to the compressor 61. As best shown in Fig. 9, the portion of the conduit 331 which extends along the rear wall of the outer cabinet shell 312 is covered by a protective sleeve 337 preferably molded thereon and made of soft rubber. The conduit 337 passes through openings in plates 338 and 339 and the hood of the refrigerating cabinet.

An arrangement for ejecting the ice or other material frozen in the pockets 324 is provided. This arrangement includes a push rod or plunger 329 for each pocket or mold 324 which is reciprocable into and out of the interior of the pockets or molds 324 as best shown in Fig. 11. Inasmuch as the interior surface of the pockets 324 are covered by a thin rubber sheet it is unnecessary to heat the molds as was done in the above described modification. I have found that the operation of the plungers 329 in conjunction with the flexible rubber lining is sufficient to break loose whatever bond exists between the frozen material and the rubber lining to eject the frozen material from the molds.

Material to be frozen is supplied to the refrigerating machine through a conduit or pipe 340 extending through the rear wall of the cabinet. If water is the material to be frozen, the conduit or pipe 340 may be connected to an ordinary water supply system or other suitable source of water. The liquid is supplied to the freezing molds of the refrigerating machine from the main supply conduit 340 through a liquid measuring arrangement which supplies just sufficient liquid

to the molds 324 substantially to fill the molds during each cycle of operation of the machine.

As best shown in Fig. 10, liquid is supplied through the pipe 340 to a supply tank 341 which is supported above the banks of molds 323 on the vertical channel framework members 423, as best shown in Fig. 8. I have provided an arrangement for maintaining liquid in the supply tank 341 at a substantially constant level which includes a float 344. Float 344 is fastened at one end of an arm 345. Arm 345 is pivotally connected to a substantially L-shaped arm 346 which is fastened in any suitable manner to the exterior of a valve casing 347. The end of arm 345 opposite the float 344 is pivotally connected to a valve stem 348 which is adapted to move vertically through an opening in the top of valve casing 347. When the level of the water in the tank 341 is lowered, the float 344 moves downwardly thus causing valve stem 348 to move upwardly to open the valve in the inlet conduit 340 thus allowing water to enter the tank 341 through an opening 349 in the valve casing 347. Water will flow into the tank 341 until the float 344 is moved upwardly to a position in which the valve stem 348 will have been moved downwardly a sufficiently great distance to close the valve and the inlet conduit 340.

Two substantially identical fluid measuring vessels 350 are arranged on the lower side of the tank 341. The measuring vessels are cup-shaped in form and the side walls thereof are substantially cylindrical. As best shown in Fig. 13, the cup-shaped vessels 350 are inserted through openings in the bottom of the tank 341 and welded thereto as indicated at 351. A cover 352 is suitably attached to the measuring vessel within the tank 341 as, for example, by cooperating threads on the exterior of the vessel 350 and the interior of the cover 352.

A dual valve is mounted in each of the fluid measuring vessels. The cover 352 is provided with an inlet opening 353 serving as a valve seat through which extends an actuating rod 354. A collar 355 is suitably fastened to the actuating rod 354. Inlet valve 356 is arranged slidably on actuating rod 354, being connected to collar 355 by means of a spring 357. An outlet opening 358 in the bottom wall of the measuring vessel 350 is arranged in vertical alignment with the inlet opening 353. Outlet opening 358 serves as a valve seat for an outlet valve 359 which is supported slidably on actuating rod 354. A cap 360 is suitably fastened as by welding to the bottom wall of measuring vessel 350 and a spring 361 is arranged between the wall of the cap 360 and the valve 358 in order to bias the outlet valve toward its closed position. An outlet conduit 362 is threaded into the threaded opening in the bottom wall of cap 360. Motion of outlet valve 359 along rod 354 is limited in one direction by a collar 364 secured to rod 354 and in the other direction by the tension of spring 361.

When the actuating rods are moved to their extreme upper positions, as illustrated in Fig. 13, the spring 361 is compressed between the outlet valve cap 360 and the valve 359, thus pressing the valve 359 against its seat in the outlet opening and closing the same. At the same time the inlet valve 356 is moved upwardly and away from its cooperating seat so that fluid within the tank 341 may flow through the opening 353 into the measuring vessels 350. In order to permit air entrapped within the measuring vessels 350 to escape and to permit the measuring vessels 350

to be filled with liquid, a vent tube 363 is provided between the interior of each measuring vessel and the atmosphere above the level of liquid within tank 341.

When the actuating rods 354 are pushed downwardly to the extreme lower position, the valve 356 is pressed against its seat to close inlet 353 thus cutting off the flow of liquid from tank 341 to the interior of the measuring vessel 350. At the same time the downward movement of the actuating rod 354 causes collar 364 to bear against valve 359 in opposition to the bias of spring 361. At the end of the movement of the actuating rod 354 the valve 359 will have been forced downwardly out of the opening 358 thus permitting the water within the measuring vessel 350 to flow out through the outlet conduit 362.

The measuring vessels 350 are designed to have such a volume that each of them will hold a volume of liquid just sufficient to fill all of the freezing molds in one of the banks of molds 323. The measuring vessels 350 supply the liquid to be frozen to the freezing molds 323 through outlet conduits 362 having Y-shaped branch outlets 366. The Y-shaped branch conduits 366 extend over the molds 323 so that liquid discharged from the lower ends thereof fills the pockets 324 and is distributed throughout the molds 323 by means of the notches 367 between the molds or pockets 324.

I have provided an arrangement for operating the valves of the measuring vessels 350 in proper sequence. The upper end of each actuating rod 354 is provided with a U-shaped extension 368. A pair of operating arms 369 are pivotally supported at one end in the U-shaped brackets as indicated at 370 and 371. The opposite ends of the operating arms 369 are pivotally supported within tank 341 in any suitable manner, as indicated at 372 and 373. Each operating arm is provided with a longitudinal slot 374 adapted to receive an operating rod 375. In order to actuate the operating arms I have provided a shaft 376 which is rotatably supported in any suitable manner within the water tank 341. At one end of shaft 376 I have provided wheel 377. The rod 375 is eccentrically mounted on the wheel 377 and is rotated thereby. At the other end of rod 376 I have provided a pinion 378 which meshes with a gear wheel 380 of comparatively large diameter as compared with pinion 379, which is rigidly mounted on a horizontal shaft 381. Shaft 381 is suitably journaled in the wall of water tank 341 and extends outside of the water tank. A pair of pawl and ratchet arrangements are provided for rotating the shaft 381 and include ratchet wheels 382 and 383 and actuating pawls 384 and 385, respectively.

Pawl 384 is pivotally connected to a notched member 386 which in turn is rigidly secured in any suitable manner to reciprocable member 388 which is part of the ejecting mechanism. As has been described above a plurality of plungers 329 is provided for ejecting the frozen material from the molds or pockets 324. In order to transmit the force necessary to cause operation of the plungers I have provided a reciprocable member 388 including two uprights 392 joined at their upper ends by a horizontal member 397. At the lower ends of members 392 is arranged a horizontal frame-work made up of side members 393 and cross-pieces 393a. Cross-pieces 394 join side members 393 intermediate of their ends. The banks of molds 323 are so fastened to channel members 423 that the push rods 329 of the 75

outer rows of molds may be fastened in a suitable manner, as by nuts 395 to the cross-pieces 393a. The cross-pieces 394 are so positioned with respect to frame members 393 that the plungers

5 329 of the inner rows of molds may be fastened thereto in a similar manner. Guide pins 397 are supported in frame members 397 and 392 and cooperate with channel 397a suitably secured to channel member 425 to guide the vertical movement of the reciprocable frame. It will be apparent that any upward movement of the ejecting frame-work will force all the plungers 329 upwardly into the molds or pockets 324 to eject the frozen material therein. In order to insure that pawl 384 will engage with ratchet wheel 382, a spring 384a has been suitably fastened to an extension 389 on the notched member 386.

In order to operate the reciprocating frame or member 388, I have provided a fluid motor utilizing the pressure of the refrigerant in the high side of the refrigerant system. I also provide a disengageable connection including pivoted lever 390 carrying an upstanding lug 391. Pawl 385 is 20 pivotally supported by lug 391 and to insure that pawl 385 will be maintained in operating relationship with ratchet wheel 383 I have provided spring 385a to bias the pawl toward the ratchet wheel. The pivoted lever 390 is hollowed out for 25 a portion of its length to receive a reciprocable trigger member 396, the end of which engages a notch 386a in the notched member 386 supported on horizontal member 397. The member 396 is biased outwardly by a spring 401. A slot 35 402 is provided in the lower side of pivoted lever 390 and lug 403, integral with trigger member 396, projects downwardly through the slot 402. An arm 404 is pivotally secured to the lug 403 at one end, the other end of arm 404 being provided 40 with an enlargement 405 having a longitudinal slot adapted to engage pin 406 which is suitably supported within the casing 407 of fluid motor 408. The lever 390 is pivotally supported within the casing 407 of the fluid motor 408 by means 45 of projections 409.

I have provided mechanism within the fluid motor 408 to cause movement of the pivoted lever 390. The casing 407 of the fluid motor 408 is provided with an upper portion having a flange 408a and a bottom plate having a flange 408b matching the flange 408a. A diaphragm 410 is rigidly supported about its circumference between the flanges 408a and 408b. A block 411 is suitably secured at the center of the diaphragm 410 and operating rod 412 is suitably secured to the block 411 as, for example, by means of screw threads on rod 412 and a tapped hole in the block 411. The operating rod 412 is biased downwardly by means of a spring 413 which extends between 50 block 411 and a portion 414 of the casing 407.

In order to operate the pivoted lever 390 I admit high pressure liquid refrigerant from the main conduit 381 through branch conduit 415, solenoid operated stop valve 416 and branch conduit 417 into the space between the bottom plate 65 of the fluid motor 408 and the diaphragm 410. The position of the diaphragm 410 therefore will be dependent upon the pressure within the space 417a. An increase of pressure within the chamber 417a will be transmitted due to the upward movement of the diaphragm 410 against the tension of the spring 413 to the pivoted lever 390 through operating rod 412 and head 418 fastened at the upper end of operating rod 412. The above 70 described operation will cause the lever 390 and

trigger member 396 to rotate in a clockwise direction about the pivot 409. Since trigger member 396 engages the notch 386a, this rotational movement will result in the upward movement of the ejecting frame-work and plungers 329. As lever 390 rotates about pivot 409, the arm 404 will gradually retract trigger 296 into the pivoted lever 390 and withdraw the trigger 396 from the notch 386a so that at a predetermined point the trigger 396 will be entirely withdrawn from the notch 386a thereby releasing the reciprocable member 388 which, moving downwardly by its own weight, will retract the operating rods 328 from within the pockets 324 of the banks of molds 323.

Ratchet member 382 is so adjusted that when the reciprocable member 388 reaches its highest vertical position, pawl 384 will engage one of the teeth of the ratchet wheel 382. As the reciprocable member 388 falls, pawl 384 will transmit a counterclockwise movement to the shaft 381 through the ratchet wheel 382. The rotation of shaft 381 will be transmitted through pinions 380 and 379, shaft 376, wheel 377 to rod 375. The rod 375 to operating arms 369.

As shown in Fig. 10, the valves 356 of the measuring apparatus are in the upward or open position. In this position the measuring cups 350 will be filled by the flow of liquid from tank 341 through the openings 353 into the measuring vessels 350. The ratios of the pinions 379 and 380 is such that when the shaft 381 is rotated by the downward movement of the reciprocable member 388, rod 375 will be moved in a clockwise direction through half a revolution. This motion of rod 375 will cause operating arms 369 to move downwardly so that the actuating rods 354 of the valves will also be moved downwardly thus closing the inlet valves to the measuring vessels 350 and at the same time opening the outlet valves in the bottoms of the measuring vessels. The liquid will then run out of the measuring vessels through conduits 362 and 366 into the banks of molds 323.

The operating arm 390 will not return immediately to its original position. When arm 390 reaches the limit of its clockwise rotation, an electrical circuit through the solenoid 460 of solenoid operated valve 416 is broken by the opening of mercury switch 400 carried in a cylindrical extension 399 of operating arm 390 permitting valve 416 to close and cut off the supply of refrigerant to chamber 417a. A return path to the refrigerant system is supplied through conduits 417 and 415a to conduit 333. Conduit 415a is a capillary tube, however, so that the return of refrigerant is comparatively slow and, consequently, the resulting decrease in pressure within chamber 417a is correspondingly slow. As the pressure in chamber 417a decreases, the energy which has been stored in spring 401 during compression is utilized to push trigger 396 outwardly and, assisted by arm 404, will tend to cause lever 390 to return to its original position. As the original position is approached, trigger 396 will be drawn across the face of member 386 against the tension of spring 401 into engagement with notch 386a.

During rotation of shaft 381 under the impetus furnished by the downward movement of the reciprocable member 388 as described above, ratchet wheel 383 will also be rotated in a counterclockwise direction. The teeth of the ratchet wheel 383 are so arranged that just before the completion of the counterclockwise movement 75

caused by the fall of the reciprocable member 388 one of the teeth on ratchet wheel 383 will be rotated into a position to engage with pawl 385. As the pressure within the chamber 417a decreases, the operating rod 412 will be moved downwardly due to the action of spring 413 thereby permitting the lever 390 to rotate in a counterclockwise direction. This movement of lever 390 will draw pawl 385 downwardly and this downward movement will be transmitted through ratchet wheel 383, shaft 381, pinions 380 and 379, shaft 376, wheel 377 to rod 375. The rod 375 is turned another half revolution and raises the operating arms 369 to reverse the positions of the valves and permit the measuring vessels to be refilled with liquid to be frozen.

When blocks of ice or other frozen material are ejected from the freezing molds by the upward movement of the plungers 329, the frozen material moves vertically upward out of the molds until it strikes angularly disposed deflecting plates 420 which are arranged above the freezing molds. The deflecting plates are supported on longitudinally extending rods 421, the opposite ends of which are journaled in suitable brackets supported on the channel members 426. Tension springs 422 are secured to the deflecting plates. The deflecting plates operate in the manner described previously to push the blocks of frozen material off of the tops of the banks of freezing molds into the storage drawer 419. Deflectors 427 supported from the vertical channel members 423 and deflectors 427a suitably secured to the inner liner 313 of the refrigerating cabinet assist in directing the frozen material to the storage drawer.

In order to prevent the subsequent melting of the ice stored in the drawer 419, I have provided an evaporator 428 suitably supported from channel members 424. If desired, heat insulation 40 may be placed above the evaporator, as in the previously described embodiment. Liquid vaporizable refrigerant passes to the evaporator coil 428 through a branch conduit 429 which communicates with the branch conduit 332 and the main conduit 331. The refrigerant vaporized by the absorption of heat from the interior of the drawer is discharged through a branch conduit 430 into the main suction conduit 336. In 50 order to maintain the pressure differences between the inlets and outlets of the evaporators 330 and 428 at substantially constant values, I have provided automatic thermostatic expansion valves 431 and 432. The thermostatic expansion valve 431 is located in the branch supply conduit 333 of the evaporator 330 while the thermostatic expansion valve 432 is located in the branch conduit 429 leading to evaporator 428. The thermostatic expansion valves 431 and 432 are of the conventional type and include bulbs 433 and 434, respectively, which are connected thereto by conduits 435 and 436, respectively. The bulbs 433 and 434 are arranged in thermal relationship with discharge conduits 335 and 436. The operation of the expansion valve has already been described.

I have provided a control arrangement for the refrigerating machine described above which serves automatically to control the operation thereof in accordance with the various requirements of the user. To provide for either continuously freezing quantities of ice or simply to store ice which has already been made and prevent its melting, I have provided a control mechanism which includes a manually operable two-position

switch 437 having movable switch arms 438 and 439 and stationary contacts 440 and 441, as shown in Fig. 10. When it is merely desired to store ice which has already been made, switch 437 is placed in its left-hand or open position. In this position refrigerant is supplied to both evaporators 320 and 428 but the ejecting mechanism and water supply mechanisms are inoperative. Under these conditions, the operation of the compressor 61 and its driving motor 62 is controlled by switch 442 having a pair of fixed contacts 443 and 444 closed by a movable bridge member 445 which is actuated by a bellows 446. This bellows is connected through a conduit 447 with a thermostatic bulb 448 arranged in heat exchange relationship with the evaporator 428. When the evaporator 428 reaches a predetermined high temperature, the expansion of the elastic fluid in the bulb 448 causes an expansion of the bellows 446 which results in the closing of the contacts 443 and 444 by the movable bridge member 445 thus completing an electric circuit for the motor 62 from the electric supply line 449 through conductor 451 and switch 451a to the motor 62. The motor 62 is connected to the other supply line 450 through conductor 452, contacts 443 and 444, bridging member 445 and conductor 453. When the evaporator 428 reaches a predetermined low temperature, the bellows contracts and moves the bridging member 445 away from the contacts 443 and 444 thus cutting off the supply of current to the motor 62 and stopping the operation of the compressor.

When the switch arm 437 is moved to the right-hand position so that the switch arms 438 and 439 engage the contacts 440 and 441, a control circuit is set up for operating the machine continuously and automatically to freeze successive quantities of ice or the like. When the apparatus is first put into operation the banks of molds 323 are filled with liquid from the ordinary supply which is, of course, comparatively warm; consequently, the elastic fluid which is contained in a thermostatic bulb 448 arranged in heat transfer relationship with respect to one of the banks of molds 323 is caused to expand. This expansion is transmitted through a conduit 455 to a bellows 456. An operating rod 457 is caused to move a bridging member 458 into or out of engagement with fixed contacts 459 and 460 according to the position of the bellows 456. Thus, an electric circuit across the contacts 459 and 460 will be closed or opened according to the temperature of the bank 423. Inasmuch as the first charge of water causes the bellows 456 to expand the bridging member 458 will remain out of contact with the contacts 459 and 460.

With the switch 437 in its right-hand position, a circuit is completed for the compressor and its driving motor 62 from supply conductor 449 through a conductor 451 and switch 451a to the motor 62. A return circuit from the motor 62 to the other supply conductor 450 is completed through conductor 457, switch arm 439, contact 441 and conductor 453. It will thus be apparent that when the switch arm 437 is in the position to provide automatic operation of the apparatus and switch 451a is closed, bellows 456 will be inoperative and the compressor will run continuously as long as both switches are closed.

When the contents of the banks of mold 323 become frozen, the temperature of the banks will have decreased to a predetermined degree of temperature at which point bellows 456 will have contracted sufficiently to cause bridging member

458 to engage fixed contacts 459 and 460. A circuit will then be completed to energize solenoid 460 of the solenoid operated valve 416. The circuit may be traced from the electric conductor 449 through conductor 461, contact 440, switch arm 438, conductor 462, mercury switch 460 and conductor 463, to solenoid 460. The return circuit is completed to the other electric supply line 450 through conductor 464, contacts 459 and 460, bridging member 458, conductor 465 and conductor 453. The flow of current through the solenoid will result in the opening of the valve 416 thus admitting refrigerant evaporator to the power element 468. When the pressure within chamber 417a has developed to a sufficiently high value, the ejecting means will be operated to force the frozen material out of the banks, as described above. When the operating arm 380 reaches its limit of travel, the contact through the mercury switch will be broken thus deenergizing the solenoid 460 permitting the valve 416 to close. The pressure within chamber 417a will thus slowly decrease by reason of the vaporized refrigerant returning to the refrigerant circuit through the capillary tube 415a. When the operating arm 380 returns to a position at the lower limit of its travel, the mercury within the mercury tube 400 will again flow to such a position within the tube as to complete the circuit through the mercury switch. In the meantime, the comparatively warm liquid which has been admitted to the molds 323 will have caused the bellows 456 to open the electrical circuit between the contacts 459 and 460. The circuit is now in the condition first described and the above sequence will be repeated as long as the switch 437 and switch 451a remain in their closed positions.

After a sufficient number of blocks of ice or the like have been frozen to meet the requirement of the operator, the switch 437 is moved to the left into its open position and the operation of the compressor 61 again restored to the control of the bellows 446 and its corresponding thermostatic bulb 448. If the operator desires to shut off the operation of the apparatus, the manually controlled switch 451a is opened and the supply of current to the driving motor 62 is thus cut off irrespective of the position of the control switch 437.

While I have shown a particular embodiment of my invention in connection with a refrigerating machine having banks of freezing molds, I do not desire my invention to be limited to the particular construction shown and described and I intend in the appended claims to cover all modifications within the spirit and scope of my invention.

What I claim as new and desire to secure by Letters Patent of the United States is:

1. A refrigerating machine for freezing successive quantities of material and automatically ejecting the material therefrom when frozen comprising in combination a mold adapted to contain a material to be frozen, means for freezing the contents of said mold, and means including a reciprocable plunger in said mold and a thermally responsive element associated with said mold and arranged for causing operation of said plunger, said element being responsive to the temperature of said mold for initiating the ejection of the frozen material from said mold.

2. A refrigerating machine for freezing successive quantities of material and automatically ejecting the material therefrom when frozen

comprising in combination a mold adapted to contain material to be frozen, refrigerating means operable in response to the temperature of the contents of said mold for supplying a cooling medium to said mold when the contents thereof reach a predetermined high temperature, ejecting means sequentially operable with respect to said refrigerating means, said ejecting means including a thermally responsive element associated with said mold and a reciprocable plunger in said mold constructed and arranged to be operated in response to operation of said thermally responsive element, said element being responsive to the temperature of the contents of said mold for initiating the ejection of the same when the temperature thereof reaches a predetermined lower value, and supply means for replenishing the contents of said mold.

3. A refrigerating machine for freezing successive quantities of material and automatically ejecting the material therefrom when frozen comprising in combination a mold adapted to contain material to be frozen, means for freezing the contents of said mold, means dependent upon freezing of the contents of said mold for ejecting the same, supply means for replenishing the contents of said mold, and means interlocking said ejecting means and said supply means for preventing the operation of said supply means prior to the operation of said ejecting means.

4. A refrigerating machine for freezing successive quantities of material and automatically ejecting the material therefrom when frozen comprising in combination a mold adapted to contain a material to be frozen, means for freezing the contents of said mold, means for heating said mold to loosen the frozen contents, means for ejecting the frozen contents from said mold, and means for causing a predetermined relation of operation of said heating means and said ejecting means.

5. A refrigerating machine for freezing successive quantities of material and automatically ejecting the material therefrom when frozen comprising in combination a mold adapted to contain a material to be frozen, means for freezing the contents of said mold, means for heating said mold to loosen the frozen contents, means for ejecting the frozen contents from said mold, and means for automatically causing successive freezing, heating, and ejecting of the contents of said mold.

6. A refrigerating machine for freezing successive quantities of material and automatically ejecting the material therefrom when frozen comprising in combination a mold adapted to contain a material to be frozen, means for freezing the contents of said mold, means for heating said mold to loosen the frozen contents, means for ejecting the frozen contents from said mold, means for replenishing the contents of said mold, and means for automatically causing successive operation of said freezing means, said heating means, said ejecting means and said replenishing means.

7. A refrigerating machine for freezing successive quantities of material and automatically ejecting the material therefrom when frozen comprising in combination a mold adapted to contain material to be frozen, means for freezing the contents of said mold, means responsive to the temperature of said mold for supplying heat to the walls of said mold when the temperature thereof reaches a predetermined low value, means

responsive to the temperature of said mold for ejecting the frozen contents thereof when the walls of said mold have been heated to a predetermined temperature, and supply means for replenishing the contents of said mold.

8. A refrigerating machine for freezing successive quantities of material and automatically ejecting the material therefrom when frozen comprising in combination a mold adapted to contain material to be frozen, means for freezing the contents of said mold, means responsive to the temperature of said mold and including heating means arranged in heat exchange relationship therewith for supplying heat to the walls of said mold when the temperature thereof reaches a predetermined low value, means responsive to the temperature of said mold and including a piston movable into and out of said mold for ejecting the frozen contents of said mold when the walls thereof have been heated to a predetermined temperature, supply means for replenishing the contents of said mold, and means interlocking said ejecting means and said supply means for preventing the operation of said supply means prior to the operation of said ejecting means.

9. A refrigerating machine for freezing successive quantities of material and automatically ejecting the material therefrom when frozen comprising in combination a mold adapted to contain material to be frozen, means including refrigerant supplying means for freezing the contents of said mold, means for ejecting the frozen contents of said mold, means for heating said mold to loosen the frozen contents, control means responsive to the temperature of said mold for starting said refrigerant supplying means and also for rendering said heating means ineffective when the contents of said mold reach a predetermined high temperature and for stopping said refrigerant supply means and for rendering said heating means effective when the contents of said mold reach a predetermined low temperature, and control means responsive to the temperature of said mold for rendering said ejecting means effective.

10. A refrigerating machine for freezing successive quantities of material and automatically ejecting the material therefrom when frozen comprising in combination a mold adapted to contain material to be frozen, means including refrigerant supplying means for freezing the contents of said mold, means for ejecting the frozen contents of said mold, means for heating said mold to loosen the frozen contents, means for replenishing the contents of the mold, control means responsive to the temperature of said mold for starting said refrigerant supplying means and also for rendering said heating means ineffective when the contents of said mold reach a predetermined high temperature and for stopping said refrigerant supply means and for rendering said heating means effective when the contents of said mold reach a predetermined low temperature, control means responsive to the temperature of said mold for rendering said ejecting means effective, and means associated with said ejecting means for rendering said supply means operable in a predetermined relation to the operation of said ejecting means.

11. A refrigerating machine for freezing successive quantities of material and automatically ejecting the material therefrom when frozen comprising in combination a mold adapted to contain material to be frozen, a refrigerant evap-

orator arranged in heat exchange relationship with said mold, means for supplying vaporizable liquid refrigerant to said evaporator, a piston arranged for movement into and out of said mold, means including a solenoid for moving said piston to eject the contents of said mold therefrom, means including an electric heating element arranged in heat exchange relationship with said mold for supplying heat to the walls of said mold, supply means for replenishing the contents of said mold, control means responsive to the temperature of the contents of said mold for starting said refrigerant supplying means and for de-energizing said heating element when the contents of said mold reaches a predetermined high temperature and also for stopping said refrigerant supplying means and for energizing said heating element when the contents of said mold reaches a predetermined low temperature, control means responsive to the temperature of said mold for energizing said solenoid when the walls of said mold have been heated to a predetermined temperature, and means operatively connected to said ejecting means for rendering said supply means operable upon a predetermined movement of said piston.

12. A refrigerating machine for freezing successive quantities of material and automatically ejecting the material therefrom when frozen comprising in combination a mold adapted to contain material to be frozen, a refrigerant evaporator arranged in heat exchange relationship with said mold, means for supplying vaporizable liquid refrigerant to said evaporator, a piston arranged for movement into and out of said mold, means including a solenoid for moving said piston to eject the contents of said mold therefrom, means including an electric heating element arranged in heat exchange relationship with said mold for supplying heat to the walls of said mold, supply means for replenishing the contents of said mold, a movable control member having a plurality of circuit controlling members associated therewith, means for moving said control member in accordance with the temperature variations of said mold, means including an electrical circuit including said refrigerant supplying means and a pair of contacts arranged to be bridged by one of said circuit controlling members for completing said circuit and thereby starting said refrigerant supplying means when the temperature of said mold reaches a predetermined maximum, means including a normally closed contactor provided with an energizing winding connected in series with said contacts for energizing said heating element when the temperature of said mold reaches a predetermined minimum, and means including a second electrical circuit comprising said solenoid and a second pair of contacts arranged to be bridged by another of said circuit controlling members for energizing said solenoid when the temperature of said mold reaches a predetermined amount above said minimum.

13. A refrigerating machine for freezing successive quantities of material and ejecting the material therefrom when frozen comprising in combination a mold, means for supplying a refrigerating medium to said mold, ejecting means for ejecting the contents of said mold when frozen, two liquid measuring vessels, means for supplying liquid from one of said measuring vessels to said mold and for simultaneously supplying liquid to the other of said measuring ves-

sels, and means operable in alternation with said last named means for supplying liquid from said other measuring vessel to said mold and for simultaneously supplying liquid to said one measuring vessel.

14. A refrigerating machine for freezing successive quantities of material and ejecting material therefrom when frozen comprising in combination a mold, means for freezing the contents of said mold, means for ejecting the contents of said mold when frozen, two liquid measuring vessels having inlets and outlets provided with inlet and outlet valves, means for supplying liquid to the inlets of said measuring vessels, means for conveying liquid from said outlets of said measuring vessels to said mold, means for alternately opening and closing said inlet and outlet valve of each of said measuring vessels, said means also being arranged for opening the inlet valve of one of said vessels and closing the outlet valve of the other of said vessels and opening the outlet valve thereof.

15. A refrigerating machine for freezing successive quantities of material and ejecting the material therefrom when frozen comprising in combination a mold, means for freezing the contents of said mold, means for ejecting the contents of said mold when frozen, two liquid measuring vessels having inlets and outlets provided with inlet and outlet valves, respectively, means including a liquid supply tank for supplying liquid to said inlets of said measuring vessels, means for conveying liquid from said outlets of said measuring vessels to said mold, means including a valve actuating rod for each of said measuring vessels for alternately opening and closing said inlet and outlet valves of each of said measuring vessels, said last mentioned means being constructed and arranged for simultaneously moving said valve actuating rods in opposite directions for opening the inlet valve of one of said vessels and closing the outlet valve thereof while closing the inlet valve of the other of said vessels and opening the outlet valve thereof in order to permit liquid to flow from one of said measuring vessels to said mold and to simultaneously permit the other of said measuring vessels to be filled from said liquid supply tank.

16. A refrigerating machine for freezing successive quantities of material and ejecting the material therefrom when frozen comprising in combination a mold, means for freezing the contents of said mold, means for ejecting the contents of said mold when frozen, two liquid measuring vessels having inlets and outlets provided with inlet and outlet valves, respectively, means including a liquid supply tank for supplying liquid to said inlets of said measuring vessels, means for conveying liquid from said outlets of said measuring vessels to said mold, means including a valve actuating rod for each of said measuring vessels for alternately opening and closing said inlet and outlet valves of each of said measuring vessels, said last mentioned means being constructed and arranged for simultaneously moving said valve actuating rods in opposite directions for opening the inlet valve of one of said vessels and closing the outlet valve thereof while closing the inlet valve of the other of said vessels and opening the outlet valve thereof in order to permit liquid to flow from one of said measuring vessels to said mold and to simul-

tanously permit the other of said measuring vessels to be filled from said liquid supply tank, and interlocking means for sequentially actuating said last named means and said ejecting means.

17. A refrigerating machine for freezing successive quantities of material and automatically ejecting the material therefrom when frozen comprising in combination a mold adapted to contain material to be frozen, a source of liquid vaporizable refrigerant, an evaporator arranged in heat exchange relationship with said mold, means for supplying liquid refrigerant from said source to said evaporator, means for ejecting frozen material from said mold, means including a heat insulated compartment arranged for receiving and storing frozen material ejected from said mold, means including a second evaporator for cooling said compartment, and means for supplying liquid refrigerant from said source to said second evaporator.

18. A self-contained refrigerating machine for making ice or the like comprising in combination a cabinet having a heat insulated compartment therein, a refrigerant liquefying unit mounted on said cabinet, a mold positioned in said compartment, means including a refrigerant evaporator for freezing the contents of said mold, means for supplying liquid refrigerant from said refrigerant liquefying unit to said evaporator, means responsive to the temperature of the contents of said mold for ejecting the same therefrom, and means for supplying successive quantities of material to be frozen to said mold.

19. A refrigerating machine for freezing successive quantities of material and automatically ejecting the material therefrom when frozen comprising in combination a plurality of molds open at the top and adapted to contain material to be frozen, means for freezing the contents of said molds, means for automatically ejecting frozen material from the open tops of said molds, means resiliently biased to a position at an angle with respect to the tops of said molds for deflecting laterally the frozen contents of the molds ejected therefrom, and means arranged below said molds for receiving the frozen contents ejected therefrom.

20. A refrigerating machine for freezing successive quantities of material and automatically ejecting the material therefrom when frozen comprising in combination a rectangular mold having a plurality of pockets therein open at the top and adapted to contain material to be frozen, means for freezing the contents of said mold, means for ejecting the frozen contents of said mold from the top of said pockets, means including a rectangular deflector plate pivotally supported adjacent one side of said mold and resiliently biased to a position at an angle with respect to the top of said mold for deflecting laterally the frozen contents of said molds ejected from the open tops of said pockets, and means for receiving the frozen contents ejected from said mold.

21. A self-contained refrigerating machine for making ice or the like comprising in combination a cabinet having a heat insulated compartment therein, a refrigerant liquefying unit mounted on said cabinet, a mold positioned in said compartment, means including a refrigerant evaporator for freezing the contents of said mold, means for supplying liquid refrigerant from said refrigerant liquefying unit to said evaporator, means responsive to the temperature of said mold for ejecting the frozen contents of said mold, means

for supplying successive quantities of material to be frozen to said mold, a container arranged in said compartment below said mold to receive frozen material ejected from said mold, means including a second evaporator arranged in said compartment for cooling material stored in said container, and means for supplying liquid refrigerant from said refrigerant liquefying unit to said second evaporator.

22. A self-contained refrigerating machine for making ice or the like comprising in combination a cabinet having a heat insulated compartment therein, a refrigerant liquefying unit mounted in said cabinet, a plurality of vertical molds arranged in a plurality of rows within said compartment, means including an evaporator arranged in heat exchange relation with said molds for freezing the contents of said molds, means for supplying liquid refrigerant from said refrigerant liquefying unit to said evaporator, means responsive to the temperature of said molds for ejecting the frozen contents of said molds, means for supplying successive quantities of material to be frozen to said molds, a container arranged in said compartment below said molds to receive material ejected from said molds, means including a second evaporator arranged in said compartment for cooling material stored in said container, and means for supplying liquid refrigerant from said refrigerant liquefying unit to said second evaporator.

23. A self-contained refrigerating machine for making ice or the like comprising in combination a cabinet having a heat insulated compartment therein, a refrigerant liquefying unit mounted in said cabinet, a plurality of vertical molds arranged in a plurality of rows within said compartment, means including an evaporator arranged in heat exchange relation with said molds for freezing the contents of said molds, means for supplying liquid refrigerant from said refrigerant liquefying unit to said evaporator, means responsive to the temperature of said molds and including a plurality of pistons movable vertically into and out of said molds for ejecting the contents therefrom, means including a supply tank and a plurality of liquid measuring vessels communicating therewith and located above said molds for supplying successive quantities of material to be frozen to said molds, a container arranged in said compartment below said molds to receive frozen material ejected from said molds, means including a second evaporator arranged in said compartment for cooling material stored in said container, and means for supplying liquid refrigerant from said refrigerant liquefying unit to said second evaporator.

24. A self-contained refrigerating machine for making ice or the like comprising in combination a cabinet having a heat insulated compartment therein provided with a door opening in one wall thereof, a heat insulated door for closing said door opening, a refrigerant liquefying unit mounted on said cabinet, a plurality of vertical molds arranged in a plurality of rows within said compartment, means including a refrigerant evaporator arranged in heat exchange relationship with said molds for freezing the contents of said molds, means for supplying liquid refrigerant from said refrigerant liquefying unit to said evaporator, means responsive to the temperature of the contents of said molds for ejecting the same therefrom, means for supplying successive quantities of material to be frozen to said molds, and a horizontally slidable drawer ar-

ranged in said compartment below said molds and in alignment with said door opening to receive material ejected from said molds, means including a second evaporator arranged in heat exchange relationship with the interior of said drawer for cooling material stored therein, and means for supplying liquid refrigerant from said refrigerant liquefying unit to said second evaporator.

25. A refrigerating machine containing refrigerant for freezing successive quantities of material and ejecting the material therefrom when frozen comprising a mold, means for freezing the contents of said mold, and means including a fluid motor for utilizing the refrigerant in said machine for ejecting the frozen contents of said mold, said refrigerant serving as the fluid in said fluid motor.

26. A refrigerating machine containing refrigerant for freezing successive quantities of material and ejecting the material therefrom when frozen comprising a mold, means for freezing the contents of said mold, and means including a fluid motor for utilizing the high pressure liquid refrigerant in said machine for ejecting the frozen contents of said mold.

27. A refrigerating machine containing a refrigerant and having a high pressure side and a low pressure side for freezing successive quantities of material and ejecting material therefrom when frozen comprising a mold, means for freezing the contents of said mold, means including a fluid motor for ejecting the contents of said mold when frozen, means for admitting high pressure refrigerant from said machine to said motor for actuating the same, and means for returning the refrigerant admitted to said motor to the low pressure side of said refrigerating machine.

28. A refrigerating machine having a high pressure side containing liquid refrigerant and a low pressure side containing vaporized refrigerant for freezing successive quantities of material and ejecting the material therefrom when frozen comprising a mold, means associated with the low pressure side of said refrigerating machine for freezing the contents of said mold, means including a fluid motor for ejecting the contents of said mold when frozen, means for admitting liquid refrigerant from the high pressure side of said machine to said motor for actuating the same, and means for conveying liquid refrigerant from said motor to the low pressure side of said refrigerating machine and means for maintaining a pressure difference between the high and low pressure sides of said refrigerating machine.

29. A refrigerating machine having a high pressure side containing liquid refrigerant and a low pressure side containing vaporized refrigerant for freezing successive quantities of material and ejecting the material therefrom when frozen comprising a mold, means associated with the low pressure side of said refrigerating machine for freezing the contents of said mold, means for ejecting the contents of said mold when frozen, said means including a fluid motor, a plunger arranged to extend into said mold and a disengageable connection between said fluid motor and said plunger, means for admitting liquid refrigerant from said high pressure side of said refrigerating machine to said fluid motor, said connection being disengaged upon a predetermined degree of actuation of said fluid motor from its initial position, and means for

retarding the return movement of said fluid motor to its initial position.

30. A refrigerating machine having a high pressure side containing liquid refrigerant and a low pressure side containing vaporized refrigerant for freezing successive quantities of material and ejecting the material therefrom when frozen comprising a mold, means associated with the low pressure side of said refrigerating machine for freezing the contents of said mold, means for ejecting the contents of said mold when frozen, said means including a fluid motor, a plunger arranged to extend into said mold and a disengageable connection between said fluid motor and said plunger, means for admitting liquid refrigerant from said high pressure side of said refrigerating machine to said fluid motor and means for disengaging said connection upon actuation of said fluid motor and ejection of the frozen contents of said mold, and means dependent upon the flow of refrigerant from said fluid motor to the low pressure side of said refrigerating machine for retarding the return movement of said fluid motor to its initial position.

31. A refrigerating machine having a high pressure side containing liquid refrigerant and a low pressure side containing vaporized refrigerant for freezing successive quantities of material and ejecting the material therefrom when frozen comprising a mold, means associated with the low pressure side of said refrigerating machine for freezing the contents of said mold, means utilizing the pressure of refrigerant on the high pressure side of said machine for ejecting the contents of said mold when frozen, and means dependent upon the actuation of said ejecting means for refilling said mold after the frozen contents thereof are ejected therefrom.

32. A refrigerating machine having a high pressure side containing liquid refrigerant and a low pressure side containing vaporized refrigerant for freezing successive quantities of material and ejecting the material therefrom when frozen including a plurality of molds, reciprocable means for ejecting the contents of said molds when frozen, means dependent upon the movement of said reciprocable means for refilling said molds after the frozen contents thereof are ejected therefrom, and means utilizing the action of refrigerant in said refrigerating machine for reciprocating said reciprocable means and for ejecting the frozen contents of said molds.

33. A refrigerating machine having a high pressure side containing liquid refrigerant and a low pressure side containing vaporized refrigerant for freezing successive quantities of material and ejecting the material therefrom when frozen including a plurality of molds, reciprocable means for ejecting the contents of said molds when frozen, means dependent upon the movement of said reciprocable means for refilling said molds after the frozen contents thereof are ejected therefrom, means including a fluid motor utilizing the refrigerant on the high pressure side of said refrigerating machine for actuating said reciprocable means in one direction to eject the frozen contents of said molds and for releasing said reciprocable means for movement in the other direction to provide for refilling said molds, and means dependent upon movement of said reciprocable means in said other direction for refilling said molds after the frozen contents thereof are ejected therefrom.

34. A refrigerating machine having a high

pressure side containing liquid refrigerant and a low pressure side containing vaporized refrigerant for freezing successive quantities of material and ejecting the material therefrom when frozen including a plurality of molds, a reciprocable member comprising a vertical frame and plungers associated with said molds for ejecting the contents of said molds when frozen upon upward movement of said reciprocable member, means including a pivoted lever for raising said reciprocable member to eject the frozen contents of said molds, means including a fluid motor utilizing the action of refrigerant in the high pressure side of said refrigerating machine for actuating said pivoted lever and said reciprocable member to eject the frozen contents of said molds, and means for supplying refrigerant from said fluid motor to the low pressure side of said refrigerating machine.

35. A refrigerating machine having a high pressure side containing liquid refrigerant and a low pressure side containing vaporized refrigerant for freezing successive quantities of material and ejecting the material therefrom when frozen including a mold, means including a reciprocable member for ejecting the contents of said mold when frozen upon movement of said reciprocable member in one direction, means including a pivoted lever for actuating said reciprocable member in one direction to eject the frozen contents of said mold and for releasing said reciprocable member for movement in the other direction, means dependent upon movement of said reciprocable member in said other direction for refilling said mold after the frozen contents thereof are ejected, means associated with said pivoted lever and said dependent means for replenishing said refilling means by movement in said other direction of said reciprocable member, means including a fluid motor and utilizing the action of refrigerant in the high pressure side of said refrigerating machine for actuating said pivoted lever and said reciprocable member to eject the frozen contents of said mold, and means for providing restricted flow of refrigerant from said fluid motor to the low pressure side of said refrigerating machine.

36. A refrigerating machine for freezing successive quantities of material and automatically ejecting the material therefrom when frozen comprising in combination a mold adapted to contain a material to be frozen, means for freezing the contents of said mold, means for ejecting the frozen contents of said mold, means for replenishing the contents of said mold, said ejecting means and said replenishing means being interlocked, and means for causing operation of said freezing means and said ejecting means according to the temperature of said mold, said means being arranged for automatically causing successive operation of said freezing means, said ejecting means and said replenishing means.

37. A refrigerating machine for freezing successive quantities of material and ejecting the material therefrom when frozen comprising in combination a mold, means for supplying a refrigerating medium to said mold, ejecting means for ejecting the contents of said mold when frozen, a liquid measuring vessel, means for supplying liquid from said measuring vessel to said mold, and means operable in alternation with said last-named means for supplying liquid to said measuring vessel.

38. A refrigerating machine for freezing suc-

cessive quantities of material and ejecting the material therefrom when frozen comprising in combination a mold, means for ejecting the contents of said mold when frozen, a plurality of liquid measuring vessels having inlets and outlets provided with inlet and outlet valves, means for supplying liquid to the inlets of said measuring vessels, means for conveying liquid from said outlets of said measuring vessels to said mold, and means for substantially simultaneously opening the inlet valve of one of said measuring vessels and closing the outlet valve of said one of said vessels or closing the inlet valve of said one of said vessels and opening the outlet valve of said one of said measuring vessels.

39. A refrigerating machine for freezing successive quantities of material and ejecting the material therefrom when frozen comprising in combination a mold, means for freezing the contents of said mold, means for ejecting the contents of said mold when frozen, a plurality of liquid measuring vessels having inlets and outlets provided with inlet and outlet valves, respectively, means including a liquid supply tank for supplying liquid to said inlets of said measuring vessels, means for conveying liquid from said outlets of said measuring vessels to said mold, means including a valve actuating rod for each of said measuring vessels for alternately opening and closing said inlet and outlet valves of each of said measuring vessels, and interlocking means for sequentially actuating said last-named means and said ejecting means.

40. A refrigerating machine for freezing successive quantities of material and automatically ejecting the material therefrom when frozen comprising in combination a mold adapted for receiving liquid to be frozen, means for freezing the contents of said mold, means for ejecting the frozen contents of said mold, control means responsive to the temperature of said mold for controlling the operation of said ejecting means and a second manually operable control means for selectively rendering said first control means operative or inoperative.

41. A refrigerating machine for freezing successive quantities of material and automatically ejecting the material therefrom when frozen comprising in combination a mold adapted to contain material to be frozen, means for freezing the contents of said mold, means for ejecting the frozen contents of said mold, means including a diaphragm to actuate said ejecting means, means including a stop valve to supply an operating fluid to said diaphragm, control means responsive to the temperature of said mold for controlling the position of said stop valve, and a second manually operable control means for selectively rendering said first control means operative or inoperative.

42. A refrigerating machine for freezing successive quantities of material and automatically ejecting the material therefrom when frozen comprising in combination a mold adapted to contain material to be frozen, means for freezing the contents of said mold, means for ejecting the frozen contents of said mold, means including a diaphragm to actuate said ejecting means, means including a stop valve to supply an operating fluid to said diaphragm, control means responsive to the temperature of said mold and the position of said ejecting means for controlling the position of said stop valve and a second manually operable control means for selectively

rendering said first control means operative or inoperative.

43. A refrigerating machine for freezing successive quantities of material and automatically ejecting the material therefrom when frozen, comprising in combination a mold adapted to contain material to be frozen, means for freezing the contents of said mold, means for ejecting the frozen contents from said mold, means includ-

ing a diaphragm to actuate said ejecting means, means including a stop valve to supply an operating fluid to said diaphragm, control means responsive to the position of said ejecting means for controlling the position of said stop valve and a second manually operable control means for selectively rendering said first control means operative or inoperative.

DONALD H. GASTON.
